UNITED STATES PATENT OFFICE

2,217,206

INTERLOCKING SYSTEM FOR RAILROADS

Neil D. Preston, Rochester, and Forest B. Hitchcock, Greece, N. Y., assignors to General Railway Signal Company, Rochester, N. Y.

Application June 12, 1937, Serial No. 147,976

33 Claims. (Cl. 246—134)

This invention relates to interlocking systems for railroads, and more particularly pertains to an interlocking system in which a miniature track layout in a control office has located thereon the controlling buttons or levers for setting up the desired routes through the actual track layout by manipulations of the entrance-exit route type as distinctive from the type of system using an individual control lever for each traffic device controlled.

The present invention relates to improvements in the interlocking system disclosed in the prior application of S. N. Wight, Ser. No. 91,322, filed July 18, 1936.

5 This invention contemplates the organization of an interlocking system in such a manner that a miniature track diagram located in the central control office corresponds to the actual track layout in the field and has located thereon initiating and completing buttons for each of the route determining points in the track layout. In other words, each signal location is represented by an initiating (or entrance) button on the track diagram, while the end of each route has associated therewith a completing (or exit) button. To establish a particular route over the trackway, the operator actuates the initiating button at the entrance to such desired route and then actuates the completing button for the exit end of that route, followed by the actuation of a starting button for initiating the code type communication part of the system into operation.

The entrance-exit manipulation of the initiating and completing buttons for a particular route sets up a route code characteristic of that route, which code is transmitted to the apparatus in the field by a code type communication system, which may be of any suitable type, but for convenience has been considered to be of the type shown in the prior patent of Judge and Bushnell Patent No. 2,082,544, granted June 1, 1937.

Inasmuch as such a communication system can transmit only a single code during any one cycle of operation, the system of the present invention allows only one route code to be set up on the control panel at any one time. When such a desired or proposed route has been set up on the control panel, suitable indicator lamps, preferably of a bluish white, are provided to illuminate the proposed route on the miniature track diagram to leave a visual record of the operator's manipulation. After the system has transmitted the route code for that particular route and the traffic devices have actually responded, suitable indications are transmitted back to the control

office to cause the proposed route indicators to be extinguished and other suitable completed route indicators to be illuminated on the track diagram to indicate the route actually set up. These completed route indicators are preferably of a red color so as to advise the operator by a distinctive indication that no route can be set up in conflict with such completed route.

5 In the event the operator should ill-advisedly set up a proposed route upon the control panel in conflict with a route already established in the field, the system will cause the transmission of the route code for the proposed route, but suitable interlocking means are provided at the field location to prevent such proposed route code from being effective to either establish its route or to interfere with the route already established. The failure of such proposed route to become effective prevents the storage of any controls at the field location which might at a future time set up such proposed route; and similarly, the system having transmitted such proposed route code cancels the storage of its related controls in the central office. In order to set up such proposed route at a later time, a new set of manipulations is required for such route.

10 However, it will be noted that the proposed route indicators on the control panel remain illuminated under such circumstances, so that the failure of such proposed route indications to be transferred to completed route indications advises the operator of the actual conflict between routes, at which time he can take such action as may be deemed expedient. These proposed route indications can, of course, be extinguished at any time by the operation of a cancelling button.

15 A similar manipulation is employed, when the operator desires to return a route to stop. He first actuates a stop button and then designates the route which is desired to be put to stop by actuating the entrance button and the exit button for that route. The transmission of the stop route code thus set up is initiated by the operation of the communication system starting button. The reception of this stop route code by the field apparatus causes such route to be returned to stop, and the transmission of proper indications to the control office.

20 The entrance-exit method of control or manipulation so characterizes the system of the present invention, that it has been aptly termed entrance-exit interlocking, or abbreviated as "NX interlocking."

25 Other objects, purposes, and characteristic features of the present invention will be in part ob-

5

vious from the accompanying drawings, and in part pointed out as the description of the invention progresses.

In describing the invention in detail, reference will be made to the accompanying drawings, in which like reference characters designate the same parts throughout the several views; in which like letters in the reference characters designate similar functions or relationships with the 5 distinctiveness between such reference characters provided by the use of distinctive preceding numerals; in which like preceding numerals in the reference characters, when applied to different letters, represent the inclusion of such devices 10 within a particular group and in which:—

Figs. 1A and 1B, when placed side by side, illustrate the circuit arrangement employed in connection with the system of the present invention for setting up the route control codes for transmission over the multiple impulse code type of 15 communication system;

Figs. 2A and 2B, when placed end to side together with Figs. 2B, 2C and 2D placed side to side, represent the decoding apparatus employed 20 at the field location for controlling the individual traffic governing devices in accordance with the route control codes received over the communication system;

Figs. 3A and 3B, when placed end to end, represent the indication transmitting and receiving parts of the code type communication system for the field station and control office respectively;

Fig. 4 illustrates the manner in which the indications received over the code type communication system are effective to control the indicating lamps associated with the miniature track diagram and control panel illustrated in Fig. 1A;

Fig. 5 illustrates certain parts of the code transmitting apparatus employed in the control office; 40 and

Fig. 6 illustrates certain parts of the code transmitting apparatus employed at the field location.

Instead of showing the complete circuit arrangement by placing a large number of sheets side by side, a simplified method of disclosure has been employed wherein all of the control circuits for any one relay are shown in a continuous relationship; while all of the circuits which that relay may control are distributed between several sheets 50 upon which that relay is shown in block form.

For the purpose of further simplifying the illustration and facilitating in the explanation thereof, the conventional parts and circuits constituting the embodiment of the invention have been shown 55 diagrammatically and certain conventional illustrations have been employed, the drawings having been made more with the idea of making clear the purpose and principles of the present invention, together with its mode of operation, than 60 with the idea of illustrating the specific construction and arrangement of parts that would probably be employed in practice.

The various relays and their contacts are illustrated in a conventional manner and symbols are 65 employed to indicate connections to the terminals of batteries or other suitable sources of electric current supply instead of showing all of the wiring connections to such terminals.

The symbols (+) and (−) are employed to 70 indicate the positive and negative terminals of suitable batteries or other sources of electric energy; and those terminals with which such symbols are used are presumed to have current flowing from the positive terminal designated (+) to 75 the negative terminal designated (−).

The symbols (B+) and (B−) indicate connections to the opposite terminals of a suitable battery, or other direct current source, which has a central or intermediate tap designated (CN); and the circuits with which these symbols are used 5 may have current flowing in one direction or the other, depending upon the particular terminal used in combination with the intermediate tap (CN).

The symbols employed with any one circuit are 10 considered to designate the terminals of the same battery or other suitable source, but as many separate sources may be used as found necessary in the practice of the invention. If alternating current is employed, then these symbols should be 15 considered to represent the instantaneous relative polarities of the respective terminals.

Where groups of devices are referred to in a general way, such devices will be designated by the letters or preceding numerals characteristic 20 of such groups instead of citing each specific reference character of such groups.

Track layout Fig. 2D.—In the accompanying drawings, the invention has been shown applied to a track layout including a stretch of double 25 track connected by a cross-over having track switches 1TSA and 1TSB, as well as including a diverging track connected to one of the main tracks by a track switch 9TS. The stretch of double track includes a main line extending from 30 a signal 2 to a signal 5, and another main line extending from a signal 3 to a signal 6. Signal 4 governs traffic from the diverging track over the track switch 9TS.

Inasmuch as the opposite ends of a crossover 35 are usually operated at the same time, the cross-over is considered as operated by a single switch machine SM, which may be of any suitable type, such, for example, as disclosed in the patent to W. K. Howe, Patent No. 1,466,903, dated September 4, 1923. However, two switch machines may be employed if desired.

It is to be understood that the invention is not limited, as thus shown, to the control of a cross-over and signals of this chosen track layout, but 45 may be applied to any desired number of switches and signals and to all types of track layouts found in interlocking plants.

The signals 2, 3, 4, 5 and 6 are assumed to be 50 color light signals giving the usual indications of green for clear, red for danger or stop, and, if an added indication is desired, yellow for caution. These signals may be of the color light type, or any other suitable type.

The control for the signals is accomplished 55 through the signal relays 2G, 3G, 4G, 5G and 6G in the usual way, so that each signal indicates stop when its respective G relay is deenergized and indicates clear when it is energized.

The track layout of Fig. 2D has been shown 60 divided into track circuit sections 1 and 8 by suitable insulated joints indicated in the usual manner. These track sections are provided with the usual track batteries and track relays of which only the track relays 1T and 8T have been shown. 65 These normally energized track circuits are wired in the usual manner to provide for fouling protection and to provide for the insulation of the crossover and track switch, such details of wiring having been omitted for the sake of simplicity in 70 the disclosure. These track circuits can of course be divided or lengthened as desired, and arranged in accordance with any of the usual practices.

The track relays 1T and 8T have respectively 75 associated therewith slow acting repeating relays

1TP and 8TP for reasons more specifically pointed out hereinafter.

The crossover including the track switches 7TSA and 7TSB is shown as operated by the switch machine 7SM and has associated therewith a switch position repeating relay 7WP (see Fig. 2B); while the track switch 9TS is shown as operated by the switch machine 9SM and has associated therewith the switch repeating relay 9WP. Each of these switch position repeating relays WP is of the polar neutral type and is energized with one polarity or the other in accordance with the normal and reverse locked positions of its associated track switch TS and switch machine SM, and is deenergized whenever its associated track switch TS is unlocked or is in operation. Such a polarized circuit for controlling a switch position repeating relay is governed through the medium of a point detector contact mechanism, such as shown, for example, in the patent to C. S. Bushnell, Patent No. 1,517,236, dated November 25, 1924.

Control panel.—In the central office, a control machine includes a control panel on which is located a track diagram corresponding to the actual track layout in the field. The track diagram has been shown in Fig. 1A as specifically related to the control features of the present invention; and has been shown in Fig. 4 as specifically related to the indication features of the present invention. Both Figs. 1A and 4 are to be considered as the same diagram, and have been shown as having a miniature cross over 7ts and a miniature turn out switch 9ts. These miniature track switches have associated therewith illuminated portions of trackway which may be constructed in a manner similar to that shown in the prior application of F. B. Hitchcock, Ser. No. 74,709, filed April 16, 1936, but are illuminated in accordance with the present invention.

On this control panel are suitable entrance buttons NB, one for each of the signal locations, so that entrance buttons 2NB, 3NB, 4NB, 5NB and 6NB correspond respectively to the locations for signals 2, 3, 4, 5 and 6. Also, an exit button XB is provided for the end of each route, shown as buttons 2XB, 3XB, 4XB, 5XB and 6XB. It is to be understood that the ends of the routes may or may not correspond to the location of the exit buttons on the miniature track diagram, as a route is usually considered to extend from one particular signal to the next signal for the same direction or to some arbitrarily chosen point.

Each entrance button NB is in the form of a knob which is rotatable from a normal biased position to a position where the index arrow on the knob is parallel to the miniature trackway and is pointing in the direction in which the route is to be cleared. When an entrance button NB is in an operated position, it energizes an associated repeater relay NR through circuits directly controlled by contacts operated by the entrance button NB, indicated in the drawings by dotted lines. In other words, each entrance button is of the self-restoring rotatable type and always assumes a normal inactive position, but when operated to an active position effects the control of a repeater relay which is provided with a stick circuit to maintain such control although the operator releases the entrance button.

The exit buttons XB are of the self-restoring push button type and operate contacts which have been shown in the drawings as connected to the buttons XB by dotted lines. These exit

buttons XB may be made visually distinctive from the entrance buttons by making them of a different color or the like, but in accordance with the present invention, it is contemplated that the only difference in this respect is in the index on such buttons which is provided in the form of an X.

Associated with the entrance and exit buttons for each signal location is a suitable signal indicator K having suitable preceding numeral to indicate the signal with which it is associated. These indicators are preferably illuminated only when their corresponding signals are cleared as shown in Fig. 4.

The entrance button repeater relays NR together with the exit buttons XB control and select suitable route relays. These route relays have been designated: route relay 3—6 for controlling traffic over the main line track from signal 3 to signal 6 in both directions; route relay 3—5 for controlling traffic in both directions between signals 3 and 5; route relay 2—5 for controlling traffic in both directions between signals 2 and 5; route relay 3—4 for controlling traffic in both directions between signals 3 and 4; and route relay 2—4 for controlling traffic in both directions between signals 2 and 4.

These route relays have associated therewith a route stick relay RS for allowing only one route relay to be energized at a time. These route relays, such as route relay 3—6, control the setting up of the route control codes which are transmitted over the code type communication system to the apparatus in the field.

Also located on the control panel in a convenient position are the buttons ST, CA and STP which are common to the whole system.

The start button ST is for starting the code type communication system into operation and effects this through the control of a change storing repeating relay CHP.

The cancelling button CA cancels any route at any time which has been set up between entrance and exit buttons NB and XB.

The stop button STP is provided for changing the route control code set up by any combination of entrance and exit buttons from a clearing code to a stop code. This stop button is preferably operated before the particular route to be put to stop has been designated by the entrance and exit buttons NB and XB. This stop button STP has associated therewith a stop route relay SR.

Communication part of the system.—It is to be understood in connection with the communication part of the system shown in Figs. 1B, 2A, 3A, 3B, 5 and 6 that reference should be made to the prior Patent No. 2,082,544 granted to Judge and Bushnell on June 1, 1937, for an exhaustive description of such code type communication system, only those parts of such description being pointed out herein as is deemed necessary for an understanding of the present invention. For convenience in comparing the parts of the present disclosure corresponding to the parts of such prior application, the same reference characters have been employed in this disclosure as were used in such prior application. Also, certain relays have been shown in block form without control circuits, but it is to be understood that these relays are controlled as shown in the above mentioned prior application.

To simplify the disclosure of the present invention, the line circuits and their related control relays at the control office and field station have

been shown in Figs. 5 and 6, together with the stepping banks which are operated in synchronism. In other words, these figures show the interrelation between the stepping-control line 5 circuit and the indication line circuit.

But a discussion of the invention readily divides itself into two main divisions, namely, transmission of control codes and transmission of indication codes. Therefore, the control part of 10 the system is shown in Figs. 1A, 1B, 2A, 2B, 2C and 2D where certain portions of Figs. 5 and 6 are of necessity repeated. Likewise, the indication part of the system has been shown in Figs. 3A and 3B where certain portions of Figs. 5 and 6 15 are also repeated. Fig. 3A, however, does not show the details of every indication relay and the circuits which they control, but only shows typical ones. Then in Fig. 4 all of the indication relays and the circuits for the indicator lamps 20 which they control have been shown in connection with the track diagram.

Although the present invention is contemplated as employed in connection with a communication system of the duplex type, that is, a 25 system which provides for the simultaneous transmission of controls and indications when both are ready for transmission, it is to be understood that any suitable communication system either of the duplex type or of the simplex type 30 may be employed, and that the system is not limited as shown to a communication system employing two separate circuits for controls and indications respectively.

A transmitting and receiving equipment is 35 located in the control office and another such equipment is located at each of the field stations. The control office and field stations are connected by a stepping and control line circuit and an indication line circuit.

40 The control and stepping line circuit is shown as including line wires 10 and 12 connecting the control office apparatus shown in Fig. 1B with the field station apparatus shown in Fig. 2A. The line wire 10 is shown as including a three- 45 position biased-to-neutral polar line relay F at the control office and a similar line relay F¹ at the field station. This control and stepping line circuit receives polar impulses as applied from a control battery CB by the pole changing contacts 50, 51, 53 and 54 of the relays PC and NC, together with an impulsing contact 52 of an impulsing relay EP.

45 The indication line circuit is shown as including line wires 14 and 16 which connect the control office apparatus shown in Fig. 3A with the field station apparatus shown in Fig. 3B. This indication line circuit receives energy from the indication battery IB and has associated therewith two message receiving relays MF and MB 60 which respectively receive the messages transmitted during the impulse and time space periods marked off on the control line circuit. At the field station the indication line circuit has associated therewith a lockout relay LO¹ having a 65 contact 156 included in the line wire 14 for determining when that field station is to transmit indications. The indications are transmitted by relays PF¹ and PB¹ respectively during the impulse and time space periods marked off on the 70 control line circuit.

The transmitting apparatus at the control office energizes the stepping and control line circuit with a series of time spaced impulses of polarities selected in accordance with the station and route 75 codes to be transmitted as set up by the manipu-

lation of the initiation and completing buttons on the miniature track diagram. Each of these series of time spaced polar impulses comprises a predetermined number of impulse and time space periods to cause a complete operating cycle 5 of the system. At the beginning of each series of impulses, a slow acting relay SA in the control office and a similar relay SA¹ at the field station is picked up. These relays SA are made sufficiently slow acting to be maintained picked up 10 between successive impulses throughout the operating cycle, although their circuits are momentarily opened during each time space period. In the control office, the SA relay has a repeater relay 2SA which is also slow acting. 15

The application of a series of impulses to the stepping and control line circuit causes the operation of the stepping relays V at the control office in synchronism with the stepping relays at each field station, one step for each time space between impulses, while the polarity of such impulses serves to select a particular field station by the picking up of the relay SO at that station and to selectively position the relays PS and NS at the selected station for registering the particular route code intended for that station. 20

The stepping relay bank at the control office includes stepping relays 1V, 2V, 3V, 4V, 5V, 6V, 7V and LV together with a half step relay VP. 30 These relays are shown in block form in Figs. 1B and 3A while their detail circuits are shown in Fig. 5, and operate in response to the operation of the line repeating relay FP in a manner completely shown and described in the prior Patent No. 2,082,544 dated June 1, 1937. 35

Similarly, the field station includes a stepping relay bank having stepping relays 1V¹, 2V¹, 3V¹, 4V¹, 5V¹, 6V¹, 7V¹ and LV¹ together with a half step relay VP¹. These relays are shown in Figs. 2A and 3B in block form while their detail circuits 40 are shown in Fig. 6, and operate in response to the line repeating relay FP¹.

Although, as above mentioned, the stepping banks at the control office and at each of the several field stations operate in synchronism, the stepping bank at the control office and the stepping bank at the selected station are the only ones which continue to operate throughout a complete cycle of operation, as suitable means is provided at each of the stations to cause the stepping operation to cease at that station as soon as the station selecting part of the operating cycle passes through a point at which there is no further possibility of that station being selected to receive a route code for such cycle of operation. 50

The station selection at the field location is accomplished by a station selecting relay SO¹ controlled as shown in detail in the prior Patent No. 2,082,544, but as the station selecting part of an operating cycle is completely disclosed in such application, only that part of the control cycle which relates to the transmission of route codes will be discussed in detail herein. It is also to be understood that any other suitable station selecting means may be employed, so that for the purpose of an understanding of the present invention only the apparatus of a single field station need be discussed in detail. 60

The control office communication apparatus also includes an impulsing relay E and its repeating relay EP, a control starting relay C, a field starting relay FC, message receiving relays MF and MB, together with a dividing relay DV. 70

The field station communication apparatus includes a starting relay CH¹, a lockout relay LO¹, 75

pulsing relays PB¹ and PF¹, a relay SB¹ which repeats the slow acting relay SA¹ as well as various other auxiliary relays employed in such a communication system. The operation of these various relays of the communication system will be described more in detail in connection with that part of the operation of the system of the present invention with which they are involved.

The communication system is normally at rest, but it can be initiated into a cycle of operation for the transmission of route codes whenever the operator desires. With the type of communication system contemplated as employed in connection with the present invention, indication codes may be transmitted on the same cycles of operation that route codes are transmitted. However, when the communication system is at rest, it can be initiated into a cycle of operation for the transmission of indications from a field station to the central office whenever a change in the indication conditions occur at such field station. Such a change in the indication conditions at the field station causes a lockout relay LO¹ at such field station to close the indication line circuit to transmit a starting impulse to the central office, which starting impulse causes the initiation of the system to transmit impulses over the stepping and control line circuit to operate the stepping banks of the control office and the field stations in synchronism so that during the ensuing cycle of operation indication impulses may be transmitted over the indication line circuit. When the cycle of operation is for the transmission of indications alone, the impulses placed upon the stepping and control line circuit are of such a character as to form a so-called phantom code so that no field station is selected to receive a route code, although the station which is transmitting indications and the control office operate throughout such cycle.

Keeping in mind this general organization of the complete communication system contemplated in connection with the particular embodiment of the invention illustrated, and particularly that station code calls are transmitted for the selection of a particular station from among a plurality of field stations after which a route control code is transmitted to a particular selected station to control the traffic governed devices at such stations, consideration may now be given to an explanation of the manner in which the codes are set up in the central office in accordance with the entrance-exit type of manipulation employed in the present invention.

Operation

The system is normally at rest, but may be initiated by the operator at any time for the transmission of route codes, as hereinafter explained. While the system is in this condition of rest, or in the period of blank as such condition is sometimes termed, the stepping and control line circuit is normally deenergized; and similarly, the major part of the relays of the system is deenergized. Those relays, which are normally energized, will have their circuits specifically pointed out in detail when their operation and functions are discussed.

Although the track switches 7TSA, 7TSB and 9TS are usually left in their last operated positions, these track switches have been shown in positions for the passage of main line traffic. The signals are normally at "stop" and as the signals are illustrated as being of the color light type, it is to be understood that the lower or red indi-

cator of each signal is normally illuminated. With the track sections 1 and 8 unoccupied, the track relays 1T and 8T are, of course, normally picked up.

Referring to Fig. 1A, all of the entrance buttons NB and exit buttons XB are in their normal positions, because they are biased to such positions, and all of the associated route relays are assumed to be deenergized either because of the acceptance of the last route set up by a train or because of the actuation of the cancelling button CA by the operator.

Entrance-exit route interlocking.—If, for example, the operator desires to set up a route from the signal 2 to the signal 4, he actuates the entrance button 2NB ninety degrees in a clockwise direction and then actuates the exit button 4XB which is of the self-restoring push button type.

Following the actuation of the entrance button 2NB and before he actuates the exit button 4XB, he glances along the miniature trackway of such route on the control panel and ascertains whether or not it has portions which are illuminated by the red completed route indicators, thereby designating such portions as included in routes already established and conflicting with the newly proposed route. If such should be the case, he knows that a route cannot be set up in conflict with such indicated route so that he does not actuate the exit button 4XB, but rather actuates the cancelling button CA. However, assuming that there are no conflicts indicated by such completed route indicators, the operator actuates exit button 4XB.

The momentary or temporary actuation of the entrance button 2NB closes a pick up circuit for the relay 2NR from (+), through a circuit including lever contact 60 in a right hand position, windings of relay 2NR, bus wire 61, back contact 62 of route stick relay RS, back contact 63 of cycle demarking relay SA, wire 62, contact 63 of the cancel button CA, to (-). As soon as the relay 2NR picks up its contacts in response to such current flow, a stick circuit is closed from (+), through a circuit including front contact 64 of relay 2NR, windings of relay 2NR, bus wire 61, back contact 62 of relay RS, back contact 63 of relay SA, to wire 62, contact 63 of cancel button CA, to (-). The current which flows in this stick circuit for the relay 2NR maintains such relay energized only until a route relay is picked up, or until the system is initiated into a cycle of operation.

The relay 2-4 is therefore picked up at the time the exit button 4XB is actuated, although the entrance button 2NB has immediately restored to its normal biased position, so that an energizing circuit is closed for the route relay 2-4 from (+), through a circuit including front contact 65 of relay 2NR, upper winding of route relay 2-4, back contact 66 of relay 2NR, back contact 67 of exit button 4XB, to (-).

As soon as the route relay 2-4 picks up, actuating its polar contacts to right hand positions in response to such current flow, a stick circuit is closed for this route relay from (B+), through a circuit including polar contact 68 in a right hand position, front contact 69 in a picked up position, lower winding of route relay 2-4, bus wire 70, winding of route stick relay RS, back contact 71 of impulsing relay E, wire 72, front contact 74 of cancelling button CA, to (CN).

It will be readily apparent that this route relay 2-4 is maintained energized wholly dependent upon its stick circuit because the exit button 75

4XB is automatically restored to its normal position as soon as the operator releases it. Also, the relay 2NR is deenergized as soon as the route relay 2-4 picks up, because the route stick relay RS, which is in series with the stick circuit for the route relay 2-4 (also all other route relays), also picks up and opens its back contact 62 deenergizing the stick circuit for the relay 2NR. It should be noted in this connection that the resistance of the lower windings of each route relay, such as relay 2-4, must be such that when connected in series with the route stick relay RS, a proper flow of current occurs to maintain that particular route relay picked up, and to also pick up the route stick relay RS.

If the operator desires to prevent the establishment of such route as represented by this route relay 2-4, all that is necessary is the actuation of the cancelling button CA which opens front contact 74 to cause the route relay 2-4 to drop away.

Before considering how a route relay causes the illumination of the proposed route indicators on the control panel and transmission of a route code to apparatus in the field through the medium of the code type communication system upon the actuation of the starting button ST, let us consider how the energized condition of the route relay 2-4 prevents the picking up of any other route relay.

If the route relay 2-4 were not picked up, the actuation of the entrance button 3NB followed by the actuation of the exit button 5XB would cause the picking up of the route relay 3-5. This is accomplished by first picking up the relay 3NR by a circuit closed from (+), through a circuit including lever contact 73 in a right hand position, winding of relay 3NR, bus wire 61, back contact 62 of relay RS, back contact 63 of relay SA, wire 82, front contact 83 of cancel button CA, to (-). Relay 3NR is maintained picked up by a stick circuit closed from (+), through a circuit including front contact 76 of relay 3NR, windings of relay 3NR, bus wire 61, back contact 62 of relay RS, back contact 63 of relay SA, wire 82, front contact 83 of cancel button CA, to (-).

With the relay 3NR picked up, a circuit is closed for the route relay 3-5 upon the actuation of the exit button 5XB from (+), through a circuit including back contact 65 of relay 2NR, front contact 77 of relay 3NR, upper winding of route relay 3-5, back contact 84 of relay 5NR, back contact 85 of exit button 5XB, to (-). The current which flows in this circuit causes the polar contacts of relay 3-5 to be actuated to right hand positions and the neutral contacts to be picked up. This closes a stick circuit for the route relay 3-5 from (B+), through a circuit including polar contact 86 in a right hand position, front contact 87, lower windings of relay 3-5, bus wire 70, windings of route stick relay RS, back contact 71 of relay E, wire 72, front contact 74 of cancelling button CA, to (CN). The picking up of the route stick relay RS, of course, deenergizes the entrance relay 3NR by the opening of back contact 62.

However, assuming the route relay 2-4 to be picked up, the route relay 3-5 can not be picked up, inasmuch as the route stick relay RS is picked up under such conditions opening the back contact 62 included in the pick up circuit for the entrance button repeater relay 3NR. In other words, the closure of a stick circuit for any one of the route relays causes the energization of the route stick relay RS which removes en-

ergy from all of the entrance button repeating relays NR and it is obvious a route relay can not be picked up without a picked up relay NR. Thus, only one route relay for the entire system can be picked up at any one time. This is true even though the system includes a large number of interlocked groups such as shown in Fig. 2D. In other words, if there were two such track layouts as shown in Fig. 2D related to each other by being placed end to end, the entrance button repeating relays NR for both groups would include the back contact 62 of relay RS in their circuits, so that only one route relay could be picked up at any one time.

It will be observed that track layouts in general, as well as the chosen layout of Fig. 2D, include parallel routes, several of which should be cleared at the same time. This can be accomplished in accordance with the present invention because the energization of the route relay 2-4, for example, is maintained only during the cycle of operation in which it causes the transmission of its route code as determined by the associated route code jumpers in a manner later to be explained. Then, as soon as the route relay 2-4 is dropped out at the end of such cycle of operation, another route relay, for example, route relay 3-6 may be picked up upon the actuation of the entrance button 3NB followed by the actuation of the exit button 6XB to cause the associated route to be cleared contemporaneously with the route from the signal 2 to the signal 4.

More specifically, the actuation of the entrance button 3NB causes the energization of its repeating relay 3NR through its pick up circuit, after which front contact 76 closes its stick circuit, all as above pointed out. The actuation of the exit button 6XB then closes a pick up circuit for the route relay 3-6 from (+), through a circuit including back contact 65 of relay 2NR, front contact 77 of relay 3NR, upper winding of relay 3-6, back contact 78 of relay 6NR, back contact 79 of exit button 6XB, to (-).

As soon as the contacts of the route relay 3-6 respond, a stick circuit is closed from (B+), through a circuit including polar contact 80 in a right hand position, front contact 81, lower winding of relay 3-6, bus wire 70, windings of route stick relay RS, back contact 71 of relay E, wire 72, front contact 74 of cancel button CA, to (CN).

With the route relay 3-6 picked up, the starting button ST may be operated to cause the communication part of the system to be initiated into operation for the transmission of the station and route codes determined by the route relay 3-6.

It will be observed that the route stick relay RS does not pick up until the stick circuit for a route relay has been closed, at which time the then picked up entrance relay NR for the first entrance button actuated is dropped away and all other relays NR are thereby prevented from picking up in response to their associated entrance buttons. In the event that the operator should actuate the entrance button 3NB and then actuate the entrance button 6NB by mistake, no route relay is picked up as a result of such an erroneous operation. This is because the same potential is placed on the opposite terminals of the route relay. For example, assuming the entrance relay 3NR to be picked up, positive potential from (+), is placed upon the left hand terminal of the route relay 3-6 through back contact 64 and front contact 77; similarly, with the route relay 6NR picked up, 70

positive potential is placed upon the right hand terminal of the route relay 3-6 through back contact 240 of relay 4NR, back contact 241 of relay 5NR and front contact 242 of relay 6NR.

5 Thus, the route relay 3-6 is prevented from picking up under such circumstances.

route indicators for the track sections in that route. With the relay 2-4P picked up, the indicators between the signals 2 and 4 are illuminated including indicators 23P, 24P and 27P.

5

More specifically, the indicator 23P receives positive energy from (+), through front contact 248; indicator 24P receives positive energy from (+), through front contact 249; and indicator 27P receives positive energy from (+), through front contact 250.

10

In a similar manner each of the proposed route indicators for the remaining routes are illuminated by their respective route repeating relays. Inasmuch as only one route relay can be picked up at any one time, as above explained, only the proposed route indicators for a single route can be illuminated at one time.

Transmission of the selected codes.—After the operator has thus designated a proposed route by the operation of its entrance and exit buttons and observed such route indicated on the control panel by the proposed route indicators, he can pursue either of two courses; namely,

he can cause the route code to be transmitted together with its station selecting code by the actuation of the start button ST, or he can cause the proposed route to be cancelled from the route relays by the actuation of the cancel button CA.

The latter course, merely opens the front contact 74 of the cancel button CA dropping the particular route relay picked up and opens the front contact 244 dropping its repeater relay so that the proposed route is no longer illuminated on the miniature track diagram.

However, the operation of the starting button ST to cause the transmission of the selected route code and its station selecting code, initiates the communication system into operation and the transmission of the proper code impulses together with the cancellation or dropping of the particular route relay at the end of such cycle of operation so that another route relay may be picked up for a succeeding cycle of operation.

Assuming a proposed route to have been set up on the panel by 3NB and 6XB resulting in the energized condition of the route relay 3-6, the operator causes the code thus selected to be transmitted over the communication system by the actuation of the starting button ST. This closes a pick up circuit for the change repeating relay CHP from (+), through a circuit including back contact 25 of relay SA, back contact 26 of relay FC, upper winding of relay CHP, wire 75, back contact 251 of the starting button ST, to (-). As soon as the relay CHP picks up, a stick circuit is closed from (+), through a circuit including back contact 30 of relay LV, front contact 31 of relay CHP, lower winding of relay CHP, to (-).

The response of the relay CHP closes a pick up circuit for the control office starting relay C from (+), through a circuit including back contact 28 of relay SA, front contact 29 of relay CHP, winding of relay C, to (-). As soon as the relay C picks up, a stick circuit is closed from (+), through a circuit including back contact 32 of relay 2SA, front contact 33 of relay C, winding of relay C, to (-).

The picking up of relay C is maintained throughout the cycle of operation inasmuch as the relays SA and 2SA are picked up in that order so that front contact 28 of the relay SA is closed to apply positive potential (+) to front contact 33 before back contact 32 of 2SA opens. However, at the end of a cycle of operation, the

route indicators for the track sections in that route. With the relay 2-4P picked up, the indicators between the signals 2 and 4 are illuminated including indicators 23P, 24P and 27P.

More specifically, the indicator 23P receives positive energy from (+), through front contact 248; indicator 24P receives positive energy from (+), through front contact 249; and indicator 27P receives positive energy from (+), through front contact 250.

In a similar manner each of the proposed route indicators for the remaining routes are illuminated by their respective route repeating relays. Inasmuch as only one route relay can be picked up at any one time, as above explained, only the proposed route indicators for a single route can be illuminated at one time.

Transmission of the selected codes.—After the operator has thus designated a proposed route by the operation of its entrance and exit buttons and observed such route indicated on the control panel by the proposed route indicators, he can pursue either of two courses; namely,

he can cause the route code to be transmitted together with its station selecting code by the actuation of the start button ST, or he can cause the proposed route to be cancelled from the route relays by the actuation of the cancel button CA.

The latter course, merely opens the front contact 74 of the cancel button CA dropping the particular route relay picked up and opens the front contact 244 dropping its repeater relay so that the proposed route is no longer illuminated on the miniature track diagram.

However, the operation of the starting button ST to cause the transmission of the selected route code and its station selecting code, initiates the communication system into operation and the transmission of the proper code impulses together with the cancellation or dropping of the particular route relay at the end of such cycle of operation so that another route relay may be picked up for a succeeding cycle of operation.

Assuming a proposed route to have been set up on the panel by 3NB and 6XB resulting in the energized condition of the route relay 3-6, the operator causes the code thus selected to be transmitted over the communication system by the actuation of the starting button ST. This closes a pick up circuit for the change repeating relay CHP from (+), through a circuit including back contact 25 of relay SA, back contact 26 of relay FC, upper winding of relay CHP, wire 75, back contact 251 of the starting button ST, to (-). As soon as the relay CHP picks up, a stick circuit is closed from (+), through a circuit including back contact 30 of relay LV, front contact 31 of relay CHP, lower winding of relay CHP, to (-).

The response of the relay CHP closes a pick up circuit for the control office starting relay C from (+), through a circuit including back contact 28 of relay SA, front contact 29 of relay CHP, winding of relay C, to (-). As soon as the relay C picks up, a stick circuit is closed from (+), through a circuit including back contact 32 of relay 2SA, front contact 33 of relay C, winding of relay C, to (-).

The picking up of relay C is maintained throughout the cycle of operation inasmuch as the relays SA and 2SA are picked up in that order so that front contact 28 of the relay SA is closed to apply positive potential (+) to front contact 33 before back contact 32 of 2SA opens. However, at the end of a cycle of operation, the

route indicators for the track sections in that route. With the relay 2-4P picked up, the indicators between the signals 2 and 4 are illuminated including indicators 23P, 24P and 27P.

More specifically, the indicator 23P receives positive energy from (+), through front contact 248; indicator 24P receives positive energy from (+), through front contact 249; and indicator 27P receives positive energy from (+), through front contact 250.

In a similar manner each of the proposed route indicators for the remaining routes are illuminated by their respective route repeating relays. Inasmuch as only one route relay can be picked up at any one time, as above explained, only the proposed route indicators for a single route can be illuminated at one time.

Transmission of the selected codes.—After the operator has thus designated a proposed route by the operation of its entrance and exit buttons and observed such route indicated on the control panel by the proposed route indicators, he can pursue either of two courses; namely,

he can cause the route code to be transmitted together with its station selecting code by the actuation of the start button ST, or he can cause the proposed route to be cancelled from the route relays by the actuation of the cancel button CA.

The latter course, merely opens the front contact 74 of the cancel button CA dropping the particular route relay picked up and opens the front contact 244 dropping its repeater relay so that the proposed route is no longer illuminated on the miniature track diagram.

However, the operation of the starting button ST to cause the transmission of the selected route code and its station selecting code, initiates the communication system into operation and the transmission of the proper code impulses together with the cancellation or dropping of the particular route relay at the end of such cycle of operation so that another route relay may be picked up for a succeeding cycle of operation.

Assuming a proposed route to have been set up on the panel by 3NB and 6XB resulting in the energized condition of the route relay 3-6, the operator causes the code thus selected to be transmitted over the communication system by the actuation of the starting button ST. This closes a pick up circuit for the change repeating relay CHP from (+), through a circuit including back contact 25 of relay SA, back contact 26 of relay FC, upper winding of relay CHP, wire 75, back contact 251 of the starting button ST, to (-). As soon as the relay CHP picks up, a stick circuit is closed from (+), through a circuit including back contact 30 of relay LV, front contact 31 of relay CHP, lower winding of relay CHP, to (-).

The response of the relay CHP closes a pick up circuit for the control office starting relay C from (+), through a circuit including back contact 28 of relay SA, front contact 29 of relay CHP, winding of relay C, to (-). As soon as the relay C picks up, a stick circuit is closed from (+), through a circuit including back contact 32 of relay 2SA, front contact 33 of relay C, winding of relay C, to (-).

The picking up of relay C is maintained throughout the cycle of operation inasmuch as the relays SA and 2SA are picked up in that order so that front contact 28 of the relay SA is closed to apply positive potential (+) to front contact 33 before back contact 32 of 2SA opens. However, at the end of a cycle of operation, the

relays SA and 2SA drop away in that order so that the front contact 28 of relay SA is opened before the back contact 32 of relay 2SA closes, thereby momentarily opening the stick circuit for relay C.

The picking up of the relay C opens its back contact 165 which prevents the field start relay FC from having further opportunity to be picked up during the ensuing cycle of operation although the presence of a starting condition may be at the field station.

The picking up of the relay C closes front contact 41 and applies energy to the buses emanating from the stepping relays which supply energy to the code contacts selected by the particular route relay then picked up.

Before considering the particular characters of the impulses applied in accordance with selections effected by the particular picked up route relay, it is believed desirable to point out the manner in which these impulses are impressed upon the control and stepping line circuit.

Energy is supplied to either the bus 47 or the bus 48 for energizing the relays PC or NC respectively depending upon the particular code selection for the first impulse. If the relay PC is picked up, a positive impulse is applied to the stepping and control line circuit from the positive terminal of the control battery CB through back contact 50 of relay NC, front contact 51 of relay PC, back contact 52 of relay EP, windings of line relay F in the control office, over the control of line 10 to the several field stations including the polar line relay F¹ at the first field station, and then over the return line 12 to the control office, through front contact 53 of the relay PC, back contact 54 of the relay NC, at the negative terminal of the battery CB.

It will be readily apparent that, if the relay NC is picked up with the relay PC dropped away, the contacts 50 and 54 apply current to the stepping and control circuit in the reverse or negative direction to the flow of current above pointed out.

The application of an impulse to the stepping line is repeated by the line relays F and causes the half step relays VP to be picked up (see Figs. 5 and 6). The operation of relay VP causes the impulsive relay R in the control office to be picked up followed by the picking up of its relay EP upon the closure of contact 95. The picking up of the relay EP opens the stepping and control line circuit at back contact 52 causing the first time space.

The deenergization of the line relays F causes the first stepping relay 1V to be picked up at the control office and at each of the field stations. The response of the stepping relay 1V at the control office causes the relay E to be deenergized followed by the deenergization of its repeater relay EP, so that the control line circuit is again energized upon the closure of back contact 52 in accordance with the then energized condition of the relays PC and NC as determined by the code selecting contacts now rendered effective through front contacts of the relay 1V picked up during such first time space period.

Such energization of the control line circuit causes the line relays F and the various relays including the half step relay VP at the control office and at each of the field stations to respond followed by the picking up of the impulsive relay E and its repeater EP so that the second time space period is impressed upon the control line circuit. The stepping relays 2V at the control

office and at each of the field stations are picked up during this second time space period.

This impulsive operation of the stepping and control line circuit continues so as to cause the stepping relays at the control office and at the selected station to progress through the complete cycle of operation.

Having discussed briefly how the impulsive is accomplished, we will now consider how the character of each impulse is determined. The picked up condition of the route relay 3-6 connects its associated code jumpers between the stepping control buses 121, 122, 123, 124, 125, 126, 127 and 128 and the bus wires 47 and 48 for the control of relays PC and NC respectively, which stepping control buses are successively rendered effective to apply the entire control code for the cycle of operation.

The complete control code may be considered as having its code elements or impulses divided into two groups. The first group includes the code elements provided for station selection, while the second group includes the code elements for the particular route to be set up at the selected station. The first element in the route control code is for determining the direction of traffic or the particular route selected, while the next three elements select the particular route, and the last element is to determine whether such route is to be cleared or put to stop. It is to be understood in this connection, however, that the uses of the elements in the route control code may be arranged in any desired order, inasmuch as the route control code is not rendered effective until after the last code element has been received at the field station.

In order to give a more clear and definite understanding with regard to the manner in which these codes are assigned to the several route relays in the field, a typical code table of the control codes is given below.

Typical code table for controls

Code No.	Station selection	Route control codes	Field route relays
1	1 2 3	4 5 6 7 8	
2	- + -	+ + + + +	
3	- + +	+ + + + +	
4	- + -	+ + + + -	
5	- + -	+ + + - + +	
6	- + -	+ + + - + +	5-3
7	- + -	+ + + - + +	5-3 stop
8	- + -	+ + + - + +	6-3
9	- + -	+ + + - + +	6-3 stop
10	- + -	+ + + - + +	
11	- + -	+ + + - + +	4-3
12	- + -	+ + + - + +	4-3 stop
13	- + -	+ + + - + +	4-2
14	- + -	+ + + - + +	4-2 stop
15	- + -	+ + + - + +	5-2
16	- + -	+ + + - + +	5-2 stop
17	- + -	+ + + - + +	
18	- + -	+ + + - + +	
19	- + -	+ + + - + +	
20	- + -	+ + + - + +	
21	- + -	+ + + - + +	3-5
22	- + -	+ + + - + +	3-5 stop
23	- + -	+ + + - + +	3-6
24	- + -	+ + + - + +	3-6 stop
25	- + -	+ + + - + +	
26	- + -	+ + + - + +	
27	- + -	+ + + - + +	3-4
28	- + -	+ + + - + +	3-4 stop
29	- + -	+ + + - + +	2-4
30	- + -	+ + + - + +	2-4 stop
31	- + -	+ + + - + +	2-5
32	- + -	+ + + - + +	2-5 stop

With reference to the above code table, it is noted that the station selecting group of code elements are indicated as being the same for all of the codes shown. However, the first group of code elements are contemplated as arranged

in a typical Baudot code fashion so as to give a total number of eight station selecting codes for three steps, sixteen for four steps, and thirty-two for five steps, etc., but for convenience and simplicity in the typical code table only the particular code employed at the field location disclosed in Figs. 2A, 2B, 2C and 2D has been shown, it being understood that each of the remaining station selecting codes may have associated therewith the same route control codes as shown associated with the particular station selecting code chosen for this station. Therefore, if the full capacity of the eight impulse cycle were employed, the code table would show 256 codes.

15 It will be noted that certain of the codes in the table are employed for route relays, but the remaining codes may be considered as spare codes for which route relays may be added, if the track layout should be enlarged or rearranged 20 to require more route codes.

25 The relays PC and NC have their right hand terminals connected to (-), while their left hand terminals are connected to buses 47 and 48 which extend through the route relay bank of the control machine (see Fig. 1A).

30 Upon the picking up of the cycle controlling relay C following the picking up of a particular route relay such as relay 3-6, circuit selections are conditioned so that the station selecting code 35 jumpers and the route code jumpers are successively rendered effective to energize the relays PC and NC for the successive impulses of the cycle of operation.

35 When the relay C picks up following the picking up of the route relay 3-6, energy is applied to the code transmitting relay NC by reason of the position of the code jumper 101 by a circuit closed from (+), through a circuit including front contact 41 of relay C, back contact 130 of relay 4V, back contact 131 of relay 6V, back contact 132 of relay 5V, back contact 133 of relay 4V, back contact 134 of relay 3V, back contact 135 of relay 2V, back contact 136 of relay 1V, code bus 121, front contact 111 of route relay 40 3-6, code jumper 101 in a lower position, bus 48, winding of relay NC, to (-). This energization of the relay NC impresses a negative impulse 45 upon the line circuit for the first impulse period. By referring to the typical code table, it will be apparent that this negative impulse agrees with the character of the first impulse for station 50 selection for code No. 23.

55 Upon the picking up of the relay 1V during the first time space period of the cycle, contact 136 shifts the application of energy to the code bus 122, which through front contact 112 of route relay 3-6 allows the code jumper 102 to determine that the second impulse applied to the line circuit shall be positive by energizing the relay PC over bus 47.

60 Upon the picking up of the relay 2V during the second time space period of the cycle, contact 135 shifts the application of energy to the code bus 123 which through front contact 113 of route relay 3-6 allows the code jumper 103 to determine that the third impulse applied to the line circuit shall be positive by energizing the relay PC over the bus 47.

65 70 In this disclosure chosen for the embodiment of the present invention, there are only three station selecting impulses, and it will be found that the characters of these impulses agree with the characters designated in the typical code table.

The remaining impulses of the cycle constitute the route control code and it will be found that these impulses have characters as designated for code No. 23 of the typical code table.

Upon the picking up of the relay 3V during the third time space period of the cycle, the contact 134 shifts the application of energy to the code bus 124 which through front contact 114 of route relay 3-6 allows the polar contact 104 of relay 3-6 in a right hand position to determine that the fourth impulse applied to the line circuit shall be negative by energizing the relay NC over the bus 48.

Upon the picking up of the relay 4V during the fourth time space period of the cycle, contact 133 shifts the application of energy to the code bus 125 which through front contact 115 of route relay 3-6 allows the code jumper 105 to determine that the fifth impulse applied to the line circuit shall be positive by energizing the relay PC over the bus 47.

Upon the picking up of the relay 5V during the fifth time space period of the cycle, contact 132 shifts the application of the energy to the code bus 126 which through front contact 116 of the route relay 3-6 allows the code jumper 106 to determine that the sixth impulse applied to the line circuit shall be negative in character by energizing the relay NC over the bus 48.

Upon picking up of the relay 6V during the sixth time space period of the cycle, contact 131 shifts the application of energy to the code bus 127 which through front contact 117 of route relay 3-6 allows the code jumper 107 to determine that the seventh impulse applied to the line circuit shall be negative by energizing the relay NC over the bus 48.

Upon the picking up of the relay 7V during the seventh time space period of the cycle, contact 130 shifts the application of energy to the code bus 128 which through front contact 118 of the route relay 3-6 allows the code contact 108 of the stop route relay SR to determine that the eighth impulse applied to the line circuit shall be positive in character by energizing the relay PC over the bus 47.

Thus, the route relay 3-6 determines the characters of the impulses for a cycle of operation for clearing a route from the signal 3 to the signal 6.

If the operator, after having cleared this route, desired to return it to stop, because of a change in his plans for the oncoming train, he first actuates the stop button STP and then identifies the route by the operation of the entrance and exit buttons for that route. Operation of button STP closes an energizing circuit for the stop route relay SR from (+), through a circuit including back contact of stop button STP, wire 137, back contact 138 of relay RS, windings of relay SR, back contact 96 of relay E, wire 82, front contact 83 of cancelled button CA, to (-). As soon as the relay SR picks up it closes a stick circuit from (+), through a circuit including front contact 139 of relay SR, windings of relay SR, back contact 96 of relay E, wire 82, front contact 83 of cancel button CA, to (-).

The operator then actuates the entrance button 3NB in a clockwise direction to its operating position followed by the actuation of the exit button 6XB which accomplishes the energization of the route relay 3-6, as above described. Then, upon the actuation of the starting button ST, the system is set into operation for 75

transmitting the code No. 24 which is the same as code No. 23 except in the character of the eighth impulse which, in this case, is negative (-).

- 5 It is believed that it will be unnecessary to go through the manner in which this stop code is transmitted other than to point out that the code contact 103 of relay SR is now picked up so that upon the picking up of the stepping relay 7V during the seventh time space period of the operating cycle, the contact 118 of route relay 3-6 allows the code contact 108 to energize the relay NC over the bus 48 for causing the eighth impulse to be negative in character.
- 15 We have now seen how the picking up of a route relay may cause the transmission of a clearing code or may cause the transmission of a stop code, so that it is believed that consideration may now well be given to the manner 20 in which the apparatus in the field station responds to such codes.

Field station reception of codes.—Before considering how the route control codes are received at the field station, it is considered expedient to briefly point out the operation of the field station code receiving unit, although reference may be made to the above mentioned Patent No. 2,082,544 dated June 1, 1937, for a detailed description of station selection and the like.

The first impulse of a cycle of operation upon the controlled and stepping line circuit including the line wires 10 and 12, is repeated by the line relay F¹ so as to energize a line repeating relay FP¹, after which a slow acting repeater relay SA¹ is picked up (see Figs. 2A and 6). The first impulse is made sufficiently long to pick up these relays in succession. The relay SA¹ remains picked up throughout the operating cycle 35 either by receiving momentary energization through the operation of the line repeating relay FP¹, or by receiving momentary energizations through the polar contact of the relay F¹. So long as the station is capable of being selected 40 or has been selected, the relay SO¹ remains picked up, but when the station fails to be selected, then the relay SO¹ drops out and the relay FP¹ ceases operation. The stepping relays V¹ and the half step relay VP¹ (not shown) are 45 controlled by the line repeating relay FP¹.

The station selecting relay SO¹ is picked up at the beginning of the cycle of operation through back contact 150 of relay SA¹ and is maintained selectively picked up dependent upon the character 50 of the first three impulses of the cycle of operation which for this station has been selected as (-), (+), (+), as seen from the typical code table for controls. This code combination has been set up by suitable code selecting jumpers, which code selecting jumpers have not been shown in the present disclosure. At the end of the station selecting impulses, the third stepping relay 3V is picked up during the third time space period and the picking up of this relay closes 55 through a special jumper (not shown), a holding circuit which maintains the station selecting relay SO¹ picked up through the remainder of the cycle of operation.

With the station selecting relay SO¹ thus having 60 been selectively maintained energized during the station selecting portion of the operating cycle, then this station is rendered responsive to the remaining impulses of the cycle of operation so as to register the particular route 65 control code intended for such station and cause

its execution into the corresponding route relay at the field station which, in turn, governs the operation of the traffic controlling devices at that station.

For each of the stepping relays for the route 5 code steps, two decoding relays are provided, one for each distinctive character of the code employed. In the embodiment of the present invention, positive and negative impulses are employed so that a relay PS is employed for each positive 10 impulse and a relay NS is employed for each negative impulse. Thus, for any particular step either a relay PS or a relay NS is picked up depending upon the character of the impulse for that step. The circuits which these relays control 15 are so organized that if both of these relays are picked up (one having been erroneously picked up), then no route code is executed at the end of the cycle of operation. A similar failure of execution occurs when a particular step 20 has been taken upon which neither of the relays PS or NS is picked up.

It is to be understood that if the present invention were employed with a code type communication system employing three distinctive 25 code conditions for each step, then three such decoding relays would be employed for each step.

Assuming that the station has been selected by the maintaining of the station selecting relay SO¹ picked up during the station selecting steps, 30 then the steps on which the route code elements are received are successively taken and the decoding relays PS and NS are conditioned for the several steps in accordance with the distinctive characteristics of the route code elements. 35

More specifically, during the third time space period of the operating cycle, the stepping relay 3V¹ is picked up which then renders available the decoding relays 4PS and 4NS, one or the other of which may be picked up depending upon the particular positive or negative character of the code 40 element transmitted for that step.

In the particular example under consideration, the code No. 23 is assumed to be transmitted, so that the fourth code element is negative in character 45 causing a circuit to be closed for the relay 4NS from (+), through a circuit including front contact 140 of relay SO¹, polar contact 141 of relay F¹ in a left hand position, back contact 142 of relay 7V¹, back contact 143 of relay 6V¹, back contact 144 of relay 5V¹, back contact 145 of relay 4V¹, front contact 146 of relay 3V¹, lower winding 50 of relay 4NS, to (-).

As soon as the relay 4NS is picked up, it closes a stick circuit which maintains it picked up 55 throughout the remainder of the cycle of operation. This stick circuit is closed by front contact 147 of relay 4NS connecting its upper winding to the bus wire 148 which receives energy from (+) through front contact 149 of relay SA¹ 60 throughout the cycle of operation.

During the fourth time space period of the operating cycle, the stepping relay 4V¹ is picked up rendering the decoding relays 5PS and 5NS subject to the character of the particular code 65 element transmitted for that step. For code No. 23, the impulse is positive so that a circuit is closed for the relay 5PS from (+), through a circuit including front contact 140 of relay SO¹, polar contact 141 of relay F¹ in a right hand position, back contact 261 of relay 7V¹, back contact 262 of relay 6V¹, back contact 263 of relay 5V¹, front contact 264 of relay 4V¹, lower windings 70 of relay 5PS, to (-).

As soon as the relay 5PS is picked up, its stick 75

circuit is closed by front contact 265 connecting its upper winding to the bus wire 148.

During the fifth time space period of the operating cycle, the stepping relay 5V¹ is picked up rendering the decoding relays 6PS and 6NS subject to the character of the code element transmitted for that step. For the code No. 23, the sixth impulse is negative in character, so that a circuit is closed for picking up the relay 6NS from (+), through a circuit including front contact 140 of relay SO¹, polar contact 141 of relay F¹ in a left-hand position, back contact 142 of relay 7V¹, back contact 143 of relay 6V¹, front contact 144 of relay 5V¹, lower winding of relay 6NS, to (-).

As soon as the relay 6NS is picked up, it closes a stick circuit by connecting its upper winding to bus wire 148 through front contact 266.

During the sixth time space period of the operating cycle, the stepping relay 6V¹ is picked up rendering the decoding relays 7PS and 7NS subject to the character of the code element transmitted for that step. For the code No. 23, the seventh impulse is negative in character, so that the relay 7NS is energized by a circuit closed from (+), through a circuit including front contact 140 of relay SO¹, polar contact 141 of relay F¹ in a left hand position, back contact 142 of relay 7V¹, front contact 143 of relay 6V¹, lower winding of relay 7NS, to (-).

As soon as the relay 7NS is picked up, it closes a stick circuit by connecting its upper winding through front contact 267 to the bus wire 148.

During the seventh time space period of the operating cycle, the stepping relay 7V¹ is picked up rendering the decoding relays 8PS and 8NS subject to the character of the code element transmitted for that step. For the code No. 23, the character of the eighth impulse is positive, so that the relay 8PS is energized by a circuit closed from (+), through a circuit including front contact 140 of relay SO¹, polar contact 141 of relay F¹ in a right hand position, front contact 261 of relay 7V¹, lower winding of relay 8PS, to (-).

As soon as the relay 8PS is picked up, it closes a stick circuit by connecting its upper winding through front contact 268 to the bus wire 148.

The end of the eighth impulse marks the end of the operating cycle, and the control and stepping line circuit is deenergized until another cycle of operation is initiated. Before the slow acting relay SA¹ drops away at the field station, the last stepping relay LV¹ is picked up by the deenergized condition of the line circuit as repeated by the relay FP¹. This picking up of the last stepping relay LV¹, completes an executing circuit for transferring the particular code registered by the decoding relays during such cycle to the route control relay corresponding to that code.

The execution of the route code No. 23, which has been assumed to have been registered upon the decoding relays PS and NS, causes the route relay 3-6R of Fig. 2C to be energized by a circuit closed from (+), through a circuit including front contact 270 of relay LV¹, back contact 271 of relay 4PS, front contact 272 of relay 4NS, back contact 273 of relay 5NS, front contact 274 of relay 5PS, back contact 275 of relay 6PS, front contact 276 of relay 6NS, back contact 277 of relay 7PS, front contact 278 of relay 7NS, back contact 279 of relay 8NS, front contact 280 of relay 8PS, wire 281, lower winding of relay 3-6R, back contact 282 of relay 6-3R, back contact 283

of relay 3-4R, back contact 284 of relay 4-3R, back contact 285 of relay 3-5R, back contact 286 of relay 5-3R, to (-).

As soon as the route relay 3-6R is picked up, a stick circuit is closed from (+), through a circuit including front contact 287 of relay 1TP, wire 288, bus wire 289, front contact 290 of relay 3-6R, lower winding of relay 3-6R, back contact 282 of relay 6-3R, back contact 283 of relay 3-4R, back contact 284 of relay 4-3R, back contact 285 of relay 3-5R, back contact 286 of relay 5-3R, to (-).

It is evident from the circuits above pointed out for the route relay 3-6R, that its pick up and stick circuits are both interlocked with the opposing or conflicting routes by including back contacts of the route relays for such conflicting routes. For example, the route relay 3-6R can not be picked up, if the route relay 6-3R is picked up for allowing the passage of traffic from signal 6 to signal 3, by reason of the open back contact 282 of relay 6-3R. Similarly, if there were a route set up from signal 3 to signal 4, back contact 283 would be open by reason of the energized condition of the route relay 3-4R.

It will be apparent that as soon as the particular route relay, corresponding to the route control code stored in the decoding relays PS and NS, is picked up and has its stick circuit closed, the executing circuit is no longer required as the route relays, such as route relay 3-6R, for example, are relatively quick acting. In other words, the particular route relay under control is completely responsive to the executing circuit prior to the dropping away of the last stepping relay LV¹ at the end of an operating cycle for the communication part of the system.

The picking up of the route relay 3-6R closes an energizing circuit for the switch machine 7SM to cause it to operate the track switches 7TSA and 7TSB to normal main line positions. This operating circuit is closed from (+), through a circuit including front contact 291, bus wire 292, front contact 293 of lock relay 7L, through the switch machine mechanism 7SM, to (-). This energization of the switch machine 7SM causes the track switches 7TSA and 7TSB to be operated to normal positions which causes the switch position repeating relay 7WP to assume a normal energized position (as shown).

As soon as the relay 7WP indicates that the track switch 7TSB is in a normal position, a circuit is closed for clearing the signal 3 by the energization of its controlling relay 3G by a circuit closed from (+), through a circuit including front contact 294 of relay 7WP, polar contact 295 of relay 7WP in a right hand position, wire 296, front contact 297 of relay 3-6R, wire 298, windings of relay 3G, to (-).

The energization of the relay 3G opens back contact 299 and closes front contact 299 which changes the indication of signal 3 from stop to clear. When the signal control relay 3G is picked up, the lock relay 7L is deenergized by the opening of its energizing circuit (not shown) thereby preventing further control of the switch machine 7SM.

A train in approach to the signal 3 accepts such clear indication and proceeds through the track section 1. The signal can be caused to automatically indicate stop in accordance with the usual practices in automatic signalling, but for convenience the slotting of the signal 3 has not been shown.

The track relay 1T in dropping away opens

front contact 300, deenergizing its slow acting repeater relay 1TP, which opens front contact 287 in the stick circuit for the route relay 3-6R, but the closure of back contact 301 of relay 1T 5 prior to the release of the relay 1TP, applies positive potential (+) to the wire 288 so that the route relay 3-6R is maintained continuously energized.

The occupancy of the track section 1 and de-10 energization of the track relay 1T of course maintains the lock relay 1L dropped away to prevent operation of the track switch 1TSB.

When the train passes through the section and beyond the signal 6 allowing the track relay 1T to 15 pick up followed by the picking up of the relay 1TP, back contact 301 is opened before the front contact 287 is closed so that the stick circuit for the route relay 3-6R is momentarily opened to allow such route relay to drop away.

20 From the above, it will be seen that a route relay is maintained picked up until a train, which has accepted its corresponding route, has completely passed out of such route. Such control of the route relay is effective to prevent the 25 picking up of a route relay for a conflicting route while such train is in the route.

If a route code for a conflicting route is registered in the decoding relays PS and NS, it can not be executed to such conflicting route relay, 30 because of the open contacts in its pick up circuit which are opened by reason of the energized condition of the route relay for the route then established. In other words, a route can not be preconditioned so as to be automatically 35 set up when a train passes from the route then established. For example, if the route relay 3-6R is picked up and a route code (code No. 11) for the route relay 4-3R is registered in the decoding relays PS and NS, then the open back 40 contact 302 of relay 3-6 prevents the energization of route relay 4-3 during the execution period.

It will be noted that the switch machine is not locked against further control until the signal 45 for the route which includes such track switch has been cleared. If it is desired to include a back contact of the lock relay of each track switch in the signal clearing circuit, then the usual control may be employed for causing the 50 lock relay to drop away as soon as the track switch has completely responded to its control, as shown, for example, in the pending application of A. Langdon, Ser. No. 91,932, filed July 22, 1936, but it is to be understood that the so-called "electric lock equivalent" is not required 55 in connection with the present invention inasmuch as a conflicting route code can not be stored at the field location to be consummated when the train leaves the route already established.

60 We have considered how the route relay 3-6R for example, can be returned to stop conditions by the passage of a train over the route from signal 3 to signal 6, but it may happen that the operator desires to return the signal 3 to stop 65 before the train accepts the route. To do this, he sends the stop route code for the route relay 3-6R, which in this case has been assigned the code No. 24, in a manner which has already been pointed out.

70 This stop route code for a particular route is registered on the decoding relay PS and NS in the same manner as pointed out for the route clearing code and the characters of the code correspond to the clearing code except in the 75 character of the eight impulse which results in

the energization of the relay 8NS instead of the relay 8PS. Thus, at the end of the operating cycle with the last stepping relay LV¹ picked up, an executing circuit is closed which energizes the upper winding of the route relay 3-6R in such a direction that its flux opposes the flux in the magnetic structure provided by the energization of its stick circuit. This reduces the magnetic flux in the relay to zero so that its contacts drop away.

More specifically, this stop route code executing circuit for relay 3-6R is closed from (+), through a circuit including front contact 270 of relay LV¹, back contact 271 of relay 4PS, front contact 272 of relay 4NS, back contact 273 of relay 5NS, front contact 274 of relay 5PS, back contact 275 of relay 6PS, front contact 276 of relay 6NS, back contact 277 of relay 7PS, front contact 278 of relay 7NS, back contact 280 of relay 8PS, front contact 279 of relay 8NS, wire 303, front contact 304 of relay 3-6R, upper windings of relay 3-6R, to (-).

It will, of course, be apparent that the dropping away of the contacts of the relay 3-6R opens the signal clearing circuit for the signal 3 at front contact 297.

Each of the route relays controls all of the track switches in its route by closing front contacts for energizing the normal or reverse control bus for each of the track switches associated with that route. For example, front contact 415 of relay 2-4R supplies positive energy (+) to the normal control bus wire 292 for the switch machine 1SM, while front contact 305 supplies positive energy (+) to the reverse control bus 35 wire 306 for the switch machine 9SM.

Although the track layout chosen for the present disclosure involves the control of only two switch machines, it is to be understood that as many switch machines may be controlled by a 40 single route relay as the particular track layout in practice requires.

Another feature of the present invention is the manner in which the route relay for a particular route is maintained picked up dependent upon the 45 last track circuit section in the route with which it is associated. The particular route relay 3-6R described for controlling the route between signal 3 and signal 6 involves only a single track circuit, but when the signal 3 is cleared by the route relay 3-4R, for example, such route relay is made dependent upon the last track circuit section for that route, which is assumed in this case to be track section 8. Perhaps this will be best understood by assuming that the route relay 3-4R has 50 been picked up by its route control code and is thereafter dependent upon its stick circuit closed from (+), through a circuit including front contact 313 of track repeating relay 8TP, wire 314, bus wire 315, front contact 316 of route relay 60 3-4R, lower winding of route relay 3-4R, back contact 317 of route relay 4-3R, back contact 318 of route relay 3-5R, back contact 319 of route relay 5-3R, back contact 302 of route relay 3-6R, back contact 320 of route relay 6-3R, wire 321, back contact 322 of route relay 5-2R, back contact 323 of route relay 2-5R, back contact 324 of route relay 4-2R, back contact 325 of route relay 2-4R, to (-).

Energy is supplied to this stick circuit through 70 back contact 326 of relay 8T when the track section 8 becomes occupied prior to the opening of front contact 313 of the repeating relay 8TP. But after the train has passed through the track sections 1 and 8, and into the next adjoining track 75

section, the relays 8T and 8TP become energized in that order momentarily opening the stick circuit for the route relay 3-4R during the pickup period of the track repeating relay 8TP. This causes the route relay 3-4R to be dropped away releasing the locking which prevents conflicting route relays from being picked up. If the route 4-3R is picked up for a route in the opposite direction from signal 4 to the signal 3, then the route relay 4-3R is energized by its stick circuit dependent upon the track section 1 as the heel of its contact 327 is connected to the bus 289.

Transmission of indications.—Although only the transmission of controls has been considered in detail up to the present point in the description, it is to be understood that the setting up of a route and the passage of traffic through the route results in the transmission of suitable indications to the central office to advise the operator of traffic conditions.

As above explained, the line circuits and their related control relays at the control office and field station have been shown in Figs. 5 and 6, together with the stepping banks which are operated in synchronism. In other words, these Figs. 5 and 6 show the inter-relation between the stepping-control line circuit and the indication line circuit.

However, a discussion of the transmission of indications is more particularly directed to the indication line circuit and to the related control relays, so that Figs. 3A and 3B have been shown as including the indication line wires 14 and 16 together with the related control relays and the stepping relays shown in block form. The relays from which indications are transmitted are shown in Fig. 3B while typical indication receiving relays are shown in Fig. 3A, together with a typical station registration bank. Fig. 3A, however, does not show the details of all indication receiving relays and the circuits which they control, but only shows typical indication receiving relays, while Fig. 4 discloses in detail all of the indication relays and the circuits for the indicator lamps and the like, which they control.

With reference to Fig. 3B, it will be seen that each of the switch position repeating relays 7WP and 9WP have been shown in block form as well as signal control relays G and the track relays T. When any one of these relays changes its position, either picking up or dropping away, such shifting of its contacts from one position to the other momentarily opens the stick circuit for the change relay CH¹ as will be readily apparent from the drawings.

The dropping away of this relay CH¹ closes its back contact 154 and initiates the code communication part of the system into operation by energizing the lockout relay LO¹ which in turn closes a circuit for picking up the relay MB in the control office as shown in Figs. 3A and 5, which relay MB causes the system to be initiated into operation by the closure of a circuit for picking up the field starting relay FC (see Fig. 1B) closed from (+), through a circuit including front contact 162 of relay MB, back contact 163 of relay 2SA, back contact 164 of relay LV, back contact 165 of control office starting relay C, upper winding of relay FC, to (-). The picking up of this relay FC opens its back contact 26 preventing a control office start and also closes its front contact 166 to apply a negative impulse upon the control line circuit by the energization of the relay NC.

This initiates a cycle of operation in which all negative impulses are placed upon the control line circuit for causing the stepping mechanisms to operate in synchronism. The code thus placed upon the control and stepping line circuit fails to select a field station for receiving a route control code, and is therefore termed "a phantom code."

During the first impulse placed upon the stepping and control line circuit, which is relatively longer than the succeeding impulses in the cycle of operation, the particular field station at which a change has occurred has its lockout relay LO selected, provided there is no other field station closer to the control office at which a change has occurred. The picked up condition of this lockout relay, such as relay LO¹, causes the stepping bank at its field station to operate through the cycle of operation by reason of the closure of front contact 109 (see Fig. 6).

The detailed operation of the communication part of the system will not be discussed inasmuch as this has been fully disclosed in the above mentioned prior Patent No. 2,082,544 dated June 1, 1937. In this connection, it is believed sufficient for an understanding of the present invention to know that on each of the impulse and time space periods marked off on the control line circuit, an indication is transmitted over the line wires 14 and 16 to the central office. More specifically, relay PF¹ transmits to the message receiving relay MF during each impulse period of the operating cycle, while relay PB¹ transmits to the message receiving relay MB during each time space period of the operating cycle.

The first part of the operating cycle is for station registration. Therefore, the indication conditions impressed upon the indication line circuit, including line wires 14 and 16, by the code transmitting relays PB¹ and PF¹ are determined by the station code jumpers (not shown), and the resulting code is registered in the central office by selectively conditioning the registration relays 1PB, 1PF and 2PB in that order in accordance with such code. Then the station relay 1ST is picked up as soon as the last station registration code element has been transmitted, which is upon the closure of front contact 223 of the stepping relay 3V. The energization of the station relay 1ST then closes its front contacts to render the indication storage relays subject to the code elements transmitted during the remaining steps of the operating cycle.

For example, with the stepping relay 1V¹ already picked up and the relay VP¹ dropped away, the relay PF¹ is picked up during the second time space period in the operating cycle by a circuit closed from (+), through a circuit including front contact 330 of relay 7WP, polar contact 331 of 7WP in a right hand position, front contact 332 of stepping relay 1V¹, back contact 333 of stepping relay 3V¹, back contact 334 of stepping relay 5V¹, back contact 335 of stepping relay 7V¹, back contact 329 of half step relay VP¹, back contact 197 of relay FP¹, windings of relay PF¹, front contact 189 of relay LO¹, to (-).

This picked up condition of the relay PF¹ is maintained during the next impulse period (third) marked off on the control line circuit by reason of the picked up condition of the relay FP¹ closing its stick circuit including front contact 198 and front contact 197. During this third impulse period, front contact 199 of relay PF¹ causes the indication condition to be transmitted by closing a circuit through the line wires 14 and 16 to pick up the relay MF in the central office.

If, on the other hand, the relay **IWP** is dropped away or is in a reverse position, the indication to be transmitted would be the opposite condition, so the relay **PF¹** would have been left deenergized and the indication line circuit would be open upon such impulse period leaving the relay **MF** dropped away.

Depending upon whether the relay **MF** is picked up or dropped away upon such third impulse period, determines whether positive or negative energy is supplied to the indication storing relay upon the next (third) time space period of the operating cycle.

Assuming that the relay **MF** has been picked up by reason of the picked up condition of the relay **PF¹**, then a circuit is closed for energizing the relay **INK** from (B+), through a circuit including front contact **217** of relay **MF**, front contact **218** of relay **SA**, back contact **209** of relay **FP**, front contact **219** of relay **VP**, back contact **336** of relay **6V**, back contact **337** of relay **4V**, front contact **338** of relay **2V**, indication bus wire **504**, front contact **340** of station relay **1ST**, windings of relay **INK**, to (CN). This energization of the relay **INK** causes its polar contacts to be operated to right hand positions, but if the relay **MF** had been deenergized by reason of the transmission of the opposite indication condition, then (B-) would be applied to the above circuit through back contact **211**, so that the polar contacts of the relay **INK** would be operated to left hand positions.

In a similar manner to the operation above described in connection with the transmission of an indication from the relay **IWP**, indications are transmitted from each of the relays **IWP**, **9WP**, **2G**, **3G**, **4G**, **5G**, **6G**, **1T** and **8T** by suitably controlling the relays **PB¹** and **PF¹** for conditioning the indication line circuit. To give a better understanding of the present disclosure, the bus wires at the field station (see Fig. 3B) which lead to the code jumpers and relays to be indicated, have been numbered **401**, **402**, **403**, **404**, **405**, **406**, **407**, **408**, **409**, **410**, **411**, **412**, **413**, and **414** which are successively rendered effective in that order to condition the relays **PF¹** and **PB¹** in accordance with the station registering code and the indications to be transmitted.

In the control office (see Fig. 3A), the indication buses **501**, **502**, **503**, **504**, **505**, **506**, **507**, **508**, **509**, **510**, **511**, **512**, **513**, and **514** successively receive the indication conditions transmitted from the field station, and control the pilot relays for station registration and the indication relays for the various devices. It is noted that these buses are numbered so that bus **501**, for example, receives the indication condition as transmitted over the bus **401** at the field location, it being understood that such received condition is on a later time period in the operating cycle.

No specific code jumpers have been shown in connection with the bus wires **401**, **402** and **403**, nor has the station relay **1ST** been shown as assigned to any particular code registered on the pilot relays **1PB**, **1PF** and **2PB**, but it is to be understood that any desired code may be assigned and the code jumpers arranged in accordance with the principles of station registration as disclosed specifically in the above mentioned prior

70 Patent No. 2,082,544 dated June 1, 1937.

It will be noted that only typical examples of the indication relays, such as relays **INK**, **IRK** and **5GK** have been shown in Fig. 3A, although it is to be understood that each of the indication 75 relays **K** (with suitable preceding characters) in

Fig. 4 are suitably connected through contacts of the station relay **1ST** for receiving the indications as transmitted from their respective devices in the field station as shown in Fig. 3B.

With this understanding of the manner in 5 which the indications are transmitted from a field location to the central office, it is believed that a detailed description of the manner in which the indications are displayed will now best set forth the further features of the present invention. 10

Display of indications.—With reference to Fig. 4, we will now consider the manner in which the indications are displayed upon the control panel in response to the setting up of a route.

Considering that the operator desires to set up 15 a route from the signal **3** to the signal **6**, as discussed under the control operation of the system, he rotates the entrance button **3NB** to the right and then actuates the exit button **6XB** providing, of course, that the control panel does not 20 have any conflicting route indicated thereon. The route relay **3—6** is picked up as shown in Fig. 1A which results in the energization of its repeating relay **3—6P** by a circuit closed through front contact **351**. 25

As soon as the repeating route relay **3—6P** is picked up, a stick circuit is closed from (+), through a circuit including front contact **244** of the cancel key **CA**, polar contact **352** of the signal indication relay **6GK** in a right hand position, 30 polar contact **353** of the signal indication relay **3GK** in a left hand position, front contact **354** of the relay **3—6P**, lower winding of relay **3—6P**, to (—). Thus, the relay **3—6P** is maintained energized although the route relay **3—6** is dropped 35 away at the end of the operating cycle upon which its route control code is transmitted, and this repeating route relay **3—6P** is maintained picked up either until a signal is cleared to allow the passage of traffic over such route as indicated by 40 either the relay **3GK** or the relay **6GK**, or until the cancel key **CA** is actuated.

The immediate response of the route repeating relay **3—6P** following the actuation of the entrance and exit buttons **3NB** and **6XB** respectively, 45 causes the proposed route to be clearly indicated upon the control panel by the illumination of sections **21** and **25** by reason of the energization of the proposed route indicator lamps **21P** and **25P** through front contacts **355** and **356** respectively. 50 Such a display of the proposed route clearly indicates to the operator the route over which he proposes to send this train.

The control cycle, of course, occurs during 55 which the route control code is transmitted in response to the picking up of the route relay **3—6** and after such cycle route relay **3—6** drops away. When the track switch **7TSB** in that route has responded to such control, the system is set into a cycle of operation by a change in position of 60 its respective relay **IWP** so that its indication relays **INK** and **IRK** of Fig. 4 are positioned in accordance with the new position of the track switch. For the particular route under consideration, the track switch **7TSB** is already in a normal position so that the indicator relays **INK** and **IRK** do not need to receive indications for the present situation under consideration. 65

Following the response of the track switches, 70 the route relay **3—6P** causes the signal for such route to be cleared by the picking up of its control relay **3G**. This change in the relay **3G** causes a suitable clear indication to be transmitted to the relay **3GK** energizing it with positive potential to actuate its polar contacts to right hand posi- 75

tions. Such actuation of its polar contacts to the right, causes the route repeating relay 3-6P to be deenergized at open contact 353. It also causes the signal indicator 3K on the control panel to be illuminated by the application of positive potential (+) thereto through polar contact 357 in a right hand position.

Upon the clearing of the signal for the route, such route is no longer a proposed route but is a completed route and this is indicated to the operator by the distinctive illumination of the sections of such route by the completed route indicators 21C and 25C changing the appearance of the sections 21 and 25 on the control panel from a lunar 15 white indication to a red indication.

The completed route indicator 21C is energized by the application of positive potential through polar contact 258 in a right hand position, while the completed route indicator 25C also includes 20 the polar contact 259 of the switch indication relay 7NK in a right hand position.

When a train passes onto the route, the track relay 1T is deenergized causing the system to be initiated into operation (see Fig. 3B) so as to 25 transmit a suitable indication positioning the polar contacts of the relay 1TK of Fig. 4 to the right to illuminate the section 1 on the control panel by energizing indicator 1K which advises the operator that the route is now occupied.

30 The passage of the train from the route deenergizes the route relay 3-6R and causes the signal relay 3G to go to stop. This causes the transmission of a suitable indication to actuate the polar contacts of the relay 3GK to the left so 35 that the opening of contact 258 deenergizes the completed route indicators 21C and 25C. The picking up of the track relay also controls the polar contacts of the relay 1TK to the left deenergizing the track indicator lamp 1K so that the 40 operator is now advised that the route is free to be used again or any conflicting route may now be readily established.

It will be readily seen that, if the route between signals 3 and 6 is established for the opposite 45 direction by the actuation of the entrance button 6NB and exit button 3XB, the signal 6 will be cleared so that the clear indication is transmitted to the relay 6GK. This signal indicating relay 6GK controls the signal indicator 6K in a similar 50 manner as shown in detail for the relay 3GK. The operation of the contact 352 to a right-hand position also causes the route repeating relay 3-6P to be dropped away, while the operation of the polar contact 361 causes the completed 55 route indicators 21C and 25C to be illuminated in a similar manner as pointed out in connection with the relay 3GK.

Let us assume that the route repeating relay 3-4P is picked up because of the operation of 60 the entrance button 4NB and the exit button 3XB. Upon the initial picking up of the relay 3-4P, proposed route indicators 21P, 22P, 24P and 27P are respectively energized through contacts 362, 363, 364 and 365.

65 When the route has been completely established and the signal cleared, the proper indication is transmitted to the signal indicating relay 4GK which causes it to actuate its polar contacts to the right opening the stick circuit for the relay 2-4P at polar contacts 245 in a right hand position. The dropping of the relay 3-4P deenergizes the proposed route indicators, and the closure of polar contact 366 in a right-hand position energizes the completed route indicator 27C directly, 70 the completed route indicator 24C through polar

contact 367 of relay 9RK in a right hand position, the completed route indicator 22C through polar contact 368 of relay 1RK in a right hand position, and the completed route indicator 21C through polar contact 369 in a right hand position. 5

With the sections 21, 22, 24 and 27 thus illuminated, it will be readily apparent that each of the conflicting routes, such as a route between signal 5 and signal 2, for example, includes a section of the track diagram which is illuminated 10 so that the operator in contemplating the establishment of such a conflicting route is adequately warned against the operation of its entrance-exit buttons.

With a panel having the display of indications 15 thereon as provided in accordance with the present invention, the operator is continuously advised as to the conditions in the field and such conditions are indicated in a composite manner. The proposed route indications, for example, advise the operator as to the route which he intends to set up after he has actuated the entrance-exit buttons, the code for which does not necessarily have to be transmitted to the field, but by the actuation of the cancel key CA (see 25 Figs. 1A and 4), the opening of front contact 74 deenergizes the particular route relay that is then picked up, the opening of front contact 83 deenergizes the stop route relay SR in the event that it is a stop code that has been contemplated 30 is to be transmitted, while the opening of front contact 244 deenergizes the repeating route relay, such as route relay 3-4P, so as to extinguish the proposed route indications on the control panel. 35

Should a route be established between the signals 4 and the signals 3, for example, the completed route indicators would be illuminated, so that if the operator failed to notice the illuminated condition of the track section 24, and actually operated the entrance-exit buttons 5NB and 2XB, it will be readily apparent that the sections 23, 24 and 26 would be illuminated with the proposed route indicators. With this conflict between proposed and completed route indicators, 40 the operator would have his attention immediately drawn to the fact of such conflict before he has operated the start key ST for transmitting the proposed route code to the field. Thus, he actuates the cancel key CA to cancel such conflicting proposed route code. 45

As disclosed in Figs. 2B, 2C and 2D, a cleared signal remains clear even after the train has accepted the route until the route relay which governs such signal is dropped away. It is to be understood that automatic control may readily be inserted in such signal control so that the signal will go to stop immediately in the rear of a train. In the event such automatic control is inserted into the signal circuits, it is preferable in 60 accordance with the present invention that the relays such as relays 2GK, 3GK, 4GK, 5GK, etc., shall indicate the signal condition the same as shown and described so that upon the return to stop of a particular signal a suitable indication 65 is transmitted to the central office so that the proper indicator K will be caused to indicate in accordance with the actual condition of its respective signal.

However, the route relay governing such route 70 is not dropped away until the train has entirely left the route which means that the completed route indicators C for the control panel must continue to be illuminated until the train has entirely left the route. Thus, when such auto- 75

matic control is inserted in the signal control, that is, the circuits for relays 2G, 3G, 4G, 5G and 6G, it is necessary to transmit an indication to suitable indication relays in accordance with the 5 condition of the route relays in the field. In other words, the polar contacts 352 and 361 of relay 6GK would then be on an indication relay controlled in accordance with the condition of the route relay 6—3R; while its polar contact 370 10 would be on the same relay 6GK for the control of the indicator lamp 6K. This same division between the control of the polar contacts would also be made with regard to the remaining GK relays.

15 Having thus shown and described a centralized traffic controlling system of the entrance-exit type as one specific embodiment of the present invention, it is desired to be understood that this form is selected to facilitate in the disclosure of 20 the invention rather than to limit the number of forms which it may assume; and, it is further to be understood that various modifications, adaptations and limitations may be applied to the specific form shown to meet the requirements 25 of practice, without in any manner departing from the spirit or scope of the present invention except as limited by the appended claims.

What we claim is:

1. In a system of the character described; a 30 track layout having portions of track interconnected by track switches to form a plurality of conflicting routes; route establishing means in the field for each of the routes for controlling the track switches to set up the corresponding route;

35 control buttons of the self-restoring type identified with the opposite ends of each of said routes; means for energizing momentarily only each route establishing means in response to the joint operation of the control buttons for the opposite ends of its route; interlocking means in the field for allowing said route establishing means for only one of said plurality of conflicting routes to be energized at the same time; and means maintaining energized a momentarily energized route establishing means until after a train passes completely through the route; whereby any particular route can not be pre-conditioned to be set up by its route establishing means while there is a route conflicting with such particular route.

40 2. In a system of the type described for the control of traffic on railroads; a control office and a distant track layout connected by a communication system of the multiple impulse type, said track layout including a plurality of routes; some of which are conflicting and some of which are 45 non-conflicting; a control panel in the control office; control buttons on said control panel identifying the ends of said routes, said control buttons being of the self-restoring type; route control means for each of said routes initially energized in response to the momentary actuation of the control buttons for the opposite ends of its route so as to be rendered effective to transmit a control code over said communication system characteristic of its route; stick circuit means for maintaining energized that particular route control means initially energized by the operation of the buttons for the opposite ends of its route until and only until such route control means has completely transmitted its control code; route establishing means at said distant track layout for each of the routes being momentarily energized in response to the reception of the control code for its route except when 50 there is a route establishing means energized

5 for a conflicting route; means for maintaining energized a momentarily energized route establishing means until after a train passes through its route; whereby the transmission of a control code for a route establishing means, which is for a route conflicting with a route already established, fails to result in the establishment of a route at that time or at any subsequent time.

6 3. In a centralized traffic control system for railroads; a distant track layout having track portions interconnected by track switches to form a plurality of routes, some of which are conflicting and some of which are non-conflicting; signals for governing traffic over said routes; a multiple impulse code type communication system connecting a control office with said distant track layout; a control machine at the control office having a control panel; control buttons on said control panel for the ends of said routes; route control means for each of said routes responsive to the joint operation of only said control buttons for the opposite ends of its route so as to be rendered effective to transmit a control code over said communication system; means allowing only one of said route control means to be responsive to its control buttons at any one time so as to transmit a route control code; and means at said track layout responsive to the control codes transmitted over said communication system to operate the track switches for setting up the routes corresponding to the transmitted codes and to clear the signal for governing traffic over such routes.

7 4. In a system of remote control for railroads; a distant track layout having a plurality of routes formed by track switches; a normally at rest code type communication system connecting a control office and said distant track layout; control buttons at the control office for the ends of said routes; route control means for each of said routes energized in response to the joint operation of said control buttons for the opposite ends of its route; interlocking means for allowing only one of said route control means to be energized at any one time; code transmitting means effective, when initiated into operation, to transmit a code distinctive of that route associated with the particular route control means then energized, a starting button common to all of the routes for initiating said code transmitting means into operation; and means at said distant track layout responsive to each of the codes transmitted over said communication system to operate said track switches to set up the corresponding route.

8 5. In a system of remote control for railroads; a distant track layout having a plurality of routes formed by track portions interconnected with track switches; a normally at rest code type communication system connecting a control office with said distant track layout; a control machine in the control office having a panel upon which said track layout is represented by miniature track portions; control buttons on said control panel for the ends of said routes; route control means for each of said routes energized in response to the joint operation of said control buttons for the opposite ends of its route; interlocking means for allowing only one of said route control means to be energized at any one time; code transmitting means effective, when initiated into operation, to transmit a code over said communication system distinctive of that route associated with the particular route control means then energized; a starting button common to all 9

of said routes for initiating said code transmitting means into operation; means for illuminating the miniature track portions for each of the routes having its route control means energized; and means at said distant track layout responsive to each of the codes transmitted over said communication system to operate said track switches to set up the corresponding routes; whereby the actuation of the control buttons for the opposite ends of any particular proposed route determines the control code for that route and indicates such proposed route on the miniature track diagram so that the operator can check such proposed route before he actuates the starting button to transmit the control code to the distant track layout.

6. In a system of centralized traffic control for railroads; a control office and a distant track layout connected by a multiple impulse type communication system, said track layout including a plurality of routes formed by track switches; a control panel at the control office; control buttons of the self-restoring type located on said control panel and identified with the ends of the routes in said track layout; a cancelling button on said control panel; route control means for each of said routes initially energized in response to the momentary operation of said buttons for the opposite ends of its route so as to be rendered effective to transmit a control code over said communication system characteristic of the associated route; means for maintaining energized that particular route control means initially energized by the operation of the buttons for the opposite ends of its route until such route control means has completely transmitted its code or said cancel button has been operated; and code storing means at said track layout responsive to said codes transmitted over said communication system for storing said codes and effective to set up the corresponding routes.

7. In a switch and signal control system for railroads; a control office and a distant track layout connected by a normally at rest code type communication system, said track layout including a plurality of routes formed by track switches; a control panel at the control office; control buttons of the self-restoring type located on said control panel and identified with the ends of the routes in said track layout; a cancelling button on said control panel; a start button on said control panel; route control means for each of said routes initially energized in response to the momentary operation of said control buttons for the opposite ends of its route; means controlled by said start button for rendering an energized route control means effective to transmit a control code over said communication system characteristic of the associated route; means for maintaining energized that particular route control means initially energized by the operation of the control buttons for the opposite ends of its route until such route control means has completely transmitted its code or until said cancel button has been operated; a track diagram on said control panel having track portions corresponding to said track layout; indicators for distinctively illuminating each of said miniature track portions when energized; means for energizing those indicators associated with the miniature track portions corresponding to the track portions of the actual track layout for the particular route control means energized by the operation of the control buttons for the opposite

ends of its route, said energizing means being effective until such route is actually set up in the field or until said cancel button has been operated.

8. In a switch and signalling control system for railways, a portion of track including at least one track switch and a plurality of track sections to thereby form a route, a signal for governing traffic over said route, a relay effective when energized to control the operation of said track switch to set up the associated route and effective to clear said signal when the route has been set up, means for at times momentarily energizing said relay, stick circuit means for said relay, and means for maintaining said stick circuit closed until a train has passed into and out of the last track section of said plurality of track sections in said route.

9. In a traffic controlling system for railroads; a track layout having sections of track interconnected by track switches to form a plurality of routes; route establishing means for each route for controlling the operation of said track switches to set up the corresponding route when such route establishing means is energized; manually governing means for at times initially energizing said route establishing means, said means being effective to energize at any one time only those of said route establishing means which are for non-conflicting routes; and means for maintaining energized each of those of said route establishing means initially energized until a train has passed into and out of the associated route.

10. In a switch and signal control system for railroads; a section of track including at least one power operated track switch, a signal for governing traffic over said section of track, a track relay associated with said section and provided with a direct repeater relay, a route establishing relay effective when energized to control the operation of said power operated track switch and to clear said signal when it is safe to do so, means for at times energizing said route relay, stick circuit means for said route relay including a back contact of said track relay and a front contact of said track repeating relay in multiple, whereby said relay is maintained energized upon the clearing of a signal until a train has passed into and out of said track section.

11. In a system for governing the operation of power-operated track switches and signals of a railroad track layout, said track layout providing a number of routes between entrance and exit points; manually operable control means in a control office associated with the entrance and exit ends of said routes, route control means for each of said routes and each responsive to the joint operation of the control buttons belonging to the entrance and exit ends of that route; means effective upon operation of any one of said route control means for rendering the subsequent operation of any other control buttons ineffective to operate any other route control means; a communication system of the multiple impulse code type connecting the control office with the distant track layout and operable to transmit during an operating cycle a control code corresponding with the route control means then operated; and means at the track layout responsive to such control codes for governing the operation of the track switches and a signal for the route corresponding to the control code transmitted.

12. In a centralized traffic controlling system for railroads; a control office and a distant track layout connected by a normally at rest code type communication system, said track layout including a plurality of routes formed by track switches; a control machine in the control office having a control panel; control buttons on said control panel identifying the ends of said routes, said control buttons being of the self-restoring type; route control means for each of said routes initially energized in response to the momentary joint operation of said buttons for the opposite ends of its route so as to be rendered effective to transmit a control code; means for maintaining energized that particular route control means initially energized by the operation of the buttons for the opposite ends of its route only until such route control means has completely transmitted its code; and code storing means at said track layout responsive to said codes transmitted over said communication system for storing said codes and effective to set up the corresponding routes.
13. In a system of the character described for the control of traffic on a railroad, a track layout including track sections interconnected by track switches to form a plurality of routes, signals for governing the entrance of traffic into said routes, a route relay associated with each of said routes and effective when energized to control the power operated track switches to positions to set up its route and effective to clear the signal for such route after it is established, manually controlled means for selectively energizing said route relays, interlocking means for preventing the route relays for conflicting routes to be energized at the same time, stick circuit means for each of said route relays for maintaining it energized until a train has passed completely through its associated route.
14. In a system for controlling traffic on railroads; a control office and a distant track layout connected by a communication system of the multiple impulse code type, said track layout including a plurality of routes formed by track switches; a control machine in a central office having a control panel; self-restoring buttons on said panel for the ends of said routes; route control means individual to each of said routes and initially energized in response to the momentary joint operation of the control buttons for the opposite ends of its route, said route control means being effective when energized to transmit a control code characteristic of its route; holding means for maintaining energizing that particular route control means initially energized by the operation of the button for the opposite ends of its route until and only until such route control means has completely transmitted its control code, said holding means being effective to prevent any other route control means from being energized at the same time; and code storing means at said track layout responsive to said codes transmitted over said communication system for storing said codes and effective to set up the corresponding routes by operating the track switches to proper positions for such routes.
15. In a centralized traffic controlling system for railroads, a multiple impulse code type communication system connecting a control office and a distant track layout having track portions interconnected by track switches to form a plurality of routes some of which are conflicting and some of which are non-conflicting, signals for govern-
- ing traffic over the routes, a control machine in the control office having a control panel with a miniature track diagram of said track layout located thereon, control buttons on said panel for the ends of said routes, a route relay for each of said routes, circuit means for energizing each route relay in response to the joint operation of only the control buttons for the opposite ends of its route, interlocking means for allowing the circuit means for only one of said route relays to be effective to pick up a route relay at any one time, code transmitting means controlled by said route relays so as to transmit a code distinctive of that particular route corresponding to the route relay then picked up, and means at said distant track layout responsive to the route code transmitted over said communication system to operate said track switches to set up the corresponding route and to clear a signal for the passage of traffic over such route.
16. In a system for governing train movements over various routes of a track layout provided with power-operated track switches and signals; switch and signal control means in the field for governing the operation of the track switches and a signal for establishing each of the various routes, said switch and signal control means for any route being non-responsive to a control if a conflicting route is established; means for maintaining said switch and signal control means for a given route effective after it has once been controlled until a train has entered and left the last track circuit of such route; a control machine in a distant control office having manually operable means associated with the entrance and exit ends of the various routes; and means responsive to the joint actuation of the manually operable means for the entrance and exit ends of a given route for effecting for a limited time only the control of said switch and signal control means in the field to establish that route.
17. In a switch and signal control system of the entrance-exit type described; a control machine having a miniature track diagram of a railway track layout providing a plurality of routes between various entrance and exit points; manually operable self-restoring buttons associated with the entrance and exit points on said diagram; a number of route establishing means, one for each route operated by the joint actuation of the entrance and exit buttons belonging to the corresponding route; means rendered effective by the operation of any one of said route establishing means for preventing operation of any other route establishing means; switch and signal control means in the field temporarily governed by the particular route establishing means then operated; and means for restoring each route establishing means after such temporary governing of said switch and signal control means in the field.
18. In a switch and signal control system of the character described; a control machine having a miniature track diagram of a railroad track layout which provides a plurality of routes over track switches between various entrance and exit points; self-restoring manually operable control buttons associated with such entrance and exit points on said track diagram; a number of route establishing control means, one for each of said routes, and each initially energized in response to the joint operation of the two buttons for the opposite ends of said route; a communication system of the normally at rest code type for trans-

mitting from the control office to a distant field location a control in accordance with the route establishing means then energized; and means for maintaining energized a given route establishing means that has been initially energized by the operation of the buttons therefor only until said communication system has operated to transmit a control code for that route establishing means.

19. In an interlocking system for railroads; a track layout made up of sections of track interconnected by track switches to form a plurality of routes with signals governing traffic over such routes; manually governed means appertaining to each of said routes for setting up such route by operating the track switches to proper positions and clearing its respective signal; a miniature track diagram corresponding to said actual track layout and having route portions corresponding to said routes; means for illuminating those of said portions corresponding to a particular route proposed to be set up as conditioned by said manually governed means for that route, said means being effective only until the track switches and signals actually respond to set up such route; and means for distinctively and distinguishably illuminating those of said route portions corresponding to routes actually set up and having their signals cleared; whereby an operator is advised when a proposed route is in conflict with a route already set up.

20. In an interlocking system for railroads, a track layout having track portions interconnected by track switches to form a plurality of routes; signals for governing traffic over said routes; a switch position indicating relay means for each of said track switches; signal condition indicating relay means for each of said signals for indicating its clear and stop conditions; a control panel; a miniature track diagram on said control panel having track portions corresponding to the track portions of the actual track layout; control buttons on said panel for the ends of the routes; control means responsive to the joint operation of the control buttons for the opposite ends of a route for causing the operation of the track switches to set up such route and the clearing of a signal for governing traffic over that route; and means including a circuit network for illuminating the miniature track portions corresponding to the track portions of the actual track layout included in the routes then set up, said circuit network including contacts of said switch position indicating relay means, and energized dependent upon said signal condition indicating relay means indicating the cleared condition of the signals for such set up routes.

21. In a traffic controlling system for railroads of the type described; a control machine having a track diagram with miniature track portions corresponding to the track portions of a distant track layout, said track layout having a plurality of routes formed by track switches interconnecting the track portions and having signals for governing traffic over the routes; self-restoring control buttons associated with the track portions of the miniature track diagram at points representative of the ends of the routes in the actual track layout; route control means appertaining to each of said routes of the track layout and responsive to the momentary operation of the control buttons for the opposite ends of its route so as to be effective to transmit control conditions to the track switches and signals of the distant track layout to set up and clear the

corresponding route; proposed and completed route indicators associated with each of said miniature track portions to distinctively illuminate such track portions when energized; means for energizing the proposed route indicators for each track portion of the route having had its route control means effective to transmit control conditions, said means maintaining such proposed route indicators energized until the track switches of the associated route completely respond to set up such route; and means for energizing said completed route indicators for each of those routes actually set up and having a signal cleared therefor.

22. In a system of remote control for railroads; a distant track layout having a plurality of routes formed by track switches with signals for governing traffic over such routes; a normally at rest code type communication system connecting a control office and said distant track layout; control buttons at the control office for the ends of said routes; a stop route button common to all of said routes; route control means for each of said routes determining the clearing code of its route and energized in response to the joint operation of said control buttons for the opposite ends of its route; interlocking means for allowing only one of said route control means to be energized at any one time; code transmitting means effective, when initiated into operation, to transmit the clearing code distinctive of that route as determined by the particular route control means then energized; a starting button common to all of the routes for initiating said code transmitting means into operation; means controlled by the operation of said stop route button for causing the clearing code of each route control means to be changed to a stop route code so that said code transmitting means is effective to transmit a stop route code distinctive of that route associated with the particular route control means then energized; means at said distant track layout responsive to a clearing code transmitted over said communication system to operate said track switches to set up the corresponding route and clear a signal governing traffic thereover, and responsive to a stop route code for returning the governing signal of the route corresponding to such stop route code to stop.

23. In a system for controlling traffic on railroads; a track layout having track portions interconnected by track switches to form a plurality of routes between signal locations; a control machine in a central office having a control panel; a miniature track diagram on said control panel having track portions corresponding to the track portions of said distant track layout; self-restoring control buttons on said control panel for the ends of said routes at points corresponding to said signal locations; route control means individual to each of said routes, said route control means for any given route being rendered effective in response to the momentary joint operation of the control buttons for the opposite ends of that route to control the track switches to proper positions to set up that route and to clear a signal governing traffic over such route; indicators for distinctively illuminating each of said miniature track portions when energized; indicator control means individual to each of said routes, said indicator control means for any given route being initially rendered active in response to the rendering effective of

the corresponding route control means for energizing those indicators for the track portions of the corresponding route; and holding means for maintaining each indicator control means active only until the track switches of the corresponding route completely respond to set up such route and a signal is cleared for allowing traffic to pass over such route.

24. In a system for governing train movements over various routes of a track layout having track portions interconnected with power operated track switches and with signals for governing traffic in opposite directions over such routes; two route relays for each of the routes over said track layout, said route relays for any given route respectively being for opposite directions of traffic over such route; an energizing circuit for each of said route relays including contacts of the route relay for the opposite direction and contacts of the route relays for all conflicting routes so as to allow the route relay for only one direction of traffic in any route to be energized at one time and to allow such energization only when there is no conflicting route; separately manually operable entrance and exit buttons for the signal locations at the ends of the various routes; circuit means responsive to the actuation of the entrance button for the signal location at one end of a given route and the exit button for the signal location at the opposite end of that route for applying energy to the energizing circuit for the particular route relay for that given route which governs traffic from the designated entrance end; and means rendered effective upon the energization of one of said route relays for a given route to control the track switches of the track layout to proper positions to set up the corresponding route and to clear the signal at the entrance end of such route for the direction of traffic corresponding to such energized route relay.

25. In a switch and signal control system of the character described, a track layout having a portion of track with signals at the opposite ends of such portion to govern traffic in opposite directions and having intermediate track switches, a control machine having a miniature track diagram of said portion of track, a self-restoring entrance button on said track diagram at each point on said diagram corresponding to a signal location, a self-restoring exit button on said track diagram associated with each of said entrance buttons but being different in appearance so as to be readily distinguishable from such associated entrance button, an entrance relay associated with each of said entrance buttons, route establishing means for controlling said track switches and for clearing the signal at one end of the track portion in response to the energization of the entrance relay for said one end and the actuation of the exit button for the other end, and for controlling said track switches and clearing said signal at the other end of said track portion in response to the energization of the entrance relay for said other end and the actuation of the exit button for said one end, a pick-up circuit for each of said entrance relays controlled by the corresponding entrance button, and a stick circuit for each of said entrance relays closed upon the picking up of such entrance relay and opened upon the response of said route establishing means.

26. In a system of the character described for governing traffic over a railway track layout having track switches to provide a plurality of

routes between different signal locations, a control panel having a miniature track diagram of said track layout, a rotatable entrance button on said track diagram for each of the signal locations, each entrance button being rotatable in a direction corresponding to the direction which the corresponding signal governs traffic, a self-restoring exit button for the exit end of each of the routes through the track layout but being different in appearance from said entrance buttons, an entrance relay for each of said entrance buttons, route establishing means for controlling said track switches to set up different routes and for clearing the signals for governing traffic over such routes when actively conditioned, a pick-up circuit for each of said entrance relays controlled by the corresponding entrance button, a stick circuit for each of said entrance relays closed upon the picking up of such entrance relay and opened upon the active conditioning of said route establishing means, and circuit means controlled by the picking up of an entrance relay for the entrance end of any given route and the actuation of the exit button for that route for actively conditioning said route establishing means to set up such route and clear the signal at the entrance end of such route.

27. In a centralized traffic controlling system for railroads, a control office and a distant track layout connected by a code type communication system, said track layout including a plurality of routes formed by track switches between signal locations, a control machine in the control office having a control panel with a miniature track diagram of said track layout, self-restoring entrance buttons on said track diagram corresponding to each of the signal locations, self-restoring exit buttons on said track diagram corresponding to each of the signal locations at the exit ends of the various routes through the track layout, an entrance relay associated with each of said entrance buttons, route establishing means initially rendered effective upon the energization of an entrance relay at the entrance end of any given route and the actuation of the exit button at the opposite end of that given route for transmitting a control code characteristic of the positions of the track switches as required to set up that route and the clearing of the signal at the end corresponding to the energized entrance relay, means for maintaining said route establishing means effective only until the control code for the designated route has been completely transmitted, a pick-up circuit for each of said entrance relays controlled by its corresponding entrance button, a stick circuit for each of said entrance relays closed upon the picking up of such entrance relay only until said route establishing means has been rendered effective, and code receiving and storing means at said track layout responsive to said control codes transmitted over said communication system for storing said codes and effective to set up the corresponding routes and clear the signals at the entrance ends of such routes as designated in the control office by the operation of the entrance and exit buttons.

28. In a switch and signal control system for railroads, a track layout having a plurality of track switches to set up different routes between signal locations, certain of such routes being conflicting and others being non-conflicting, a track diagram of said track layout on a control panel, manually operable control buttons of the self-

restoring type located on the track diagram at points corresponding to the signal locations, route establishing means comprising relays rendered effective in response to the momentary actuation of a control button for a signal location at the entrance end of a route and the momentary actuation of a control button for a signal location at the exit end of a route to cause the operation of the track switches as required to set up that route and to clear the signal at the entrance end of such route, said route establishing means including circuits interlocking said relays and effective to prevent the energization of such relays as would set up any route which conflicts with a given route already set up, and means for maintaining said route establishing means effective upon the setting up of any given route until a train has passed into and out of such given route.

29. In a switch and signal control system for railroads, a track layout having sections of track interconnected by track switches to set up a plurality of routes between signal locations, said sections of track including track circuits having track relays, a track diagram control panel, said track diagram conforming to the actual track lay-out, manually operable control buttons of the self-restoring type located on said track diagram control panel at points corresponding to the signal locations, route establishing means rendered effective in response to the momentary actuation of a control button for a signal location at the entrance end of any given route and the actuation to a control button for the signal location at the exit end of that given route to cause the operation of the track switches to set up that route and to clear the signal at the entrance end of such route, said route establishing means including interlocking means to prevent the setting up of any route which conflicts with another route already set up, and circuit means controlled by said track relays for maintaining said route establishing means effective upon the setting up of any given route until a train has passed into and out of that route, whereby the setting up of any particular route by said route establishing means maintains the effectiveness of said interlocking means to prevent the establishment of a conflicting route until after a train has entered and entirely passed out of the particular route established.

30. In a switch and signal control system for railroads, a track layout having power-operated track switches for setting up different routes between signal locations, said track layout including sections of track divided into track circuits of the normally energized type, track relays for each of said track circuits, a track diagram control panel with the diagram corresponding to the actual track layout, manually operable control buttons located on said track diagram control panel at points corresponding to the signal locations, route establishing means rendered effective in response to the actuation of a control button for a signal location at the entrance end of any given route and the actuation of a control button for the signal location at the exit end of that given route to cause the operation of the track switches to establish such route and clear the signal at the entrance end of the route, said route establishing means including interlocking means to prevent the establishment of any route which conflicts with another route already established, circuit means controlled by said track relays for maintaining said route establishing means effec-

tive to prevent the establishment of a route conflicting with a route already established so long as a train is in such established route, and means controlled by said track relay for returning the signal to stop at the entrance to an established route upon the entrance of a train into such established route.

31. In a system of the character described, a track layout having a plurality of track switches to set up different routes, normally inactive manually operable control buttons of the self-restoring type for the ends of the different routes, route establishing means including control relays and rendered effective in response to the joint actuation of the control buttons for the opposite ends of any given route for momentarily energizing the control relays as required to set up that route, such control relays being interlocked to prevent the energization of the control relays for routes in conflict with said given route while its control relays are energized, and means for maintaining energized the control relays for a given route once set up so long as a train is in that route irrespective of the restoration of the control buttons at the opposite ends of said given route to normal inactive conditions.

32. A control panel for a switch and signal control system of the entrance-exit type having thereon a miniature track diagram of a railway track layout, manually operable buttons mounted on said control panel adjacent the points on said track diagram representing the ends of routes, route establishing means responsive to the operation of buttons to designate entrance and exit ends of any given route for governing the power operation of switches and the clearing of a signal for said route, indicating means including two lamps of different colors and associated with each portion of said track diagram adjacent each position of each switch and each portion intervening between switches, means responsive to the operation of said route establishing means to initiate operation of switches to set up a route and effective prior to the completion of the operation of any switch to be moved for lighting the lamps of one color for all portions of said track diagram included in said route and thereby outlining said route substantially continuously throughout its length, switch position contacts operated in accordance with the operated position of each switch, and circuits controlled by said switch position contacts for lighting the lamps of the other color associated with the various portions of said track diagram relating to the route defined by the existing position of the switches.

33. In a switch and signal control system of the entrance-exit type for a track layout having different routes extending between signal locations constituting entrance and exit points, a control panel having thereon a miniature track diagram of the track layout under the control of the operator, route control means including manually operable buttons associated with said track diagram for controlling the power operation of switches and clearing of signals for any desired route in response to the operation of buttons to designate the entrance and exit ends of such route, visual indicating means including lamps for illuminating substantially linear portions of said track diagram for the different positions of each switch and the remaining associated portions to outline each route by a substantially continuous line of light throughout its length, normal and reverse contacts associated

with each switch for reflecting the position of that switch, and a circuit network having feed points corresponding to the ends of the routes and including circuit portions controlled by said 5 normal and reverse contacts of said track switches in said track layout to form a circuit for each

established route which circuit receives energy only from a feed point corresponding to one end of that route for energizing the lamps for all the linear portions of such route.
